CODED TRACK CIRCUIT SIGNALING
SYSTEMThomas J. Judge, Rochester, N. Y., assignor to
General Railway Signal Company, Rochester,
N. Y.

Application February 14, 1941, Serial No. 378,961

31 Claims. (Cl. 246—33)

1

The present invention relates to railway signaling systems and more particularly to a railway signaling system of the absolute-permissive-block type.

For economic reasons it is important to keep the number of line wires along the railway track to a low number. In accordance with the present invention it is proposed to obtain all of the facilities and speed of operation of the signal controls heretofore enjoyed in railway signaling systems of the absolute-permissive-block type by a construction which will reduce the number of line wires below the usual three line wires heretofore used through the single track section, and the usual five line wires formerly used through the passing siding. In order to obtain these facilities it is proposed in accordance with the present invention to employ only two line wires extending from each signal location to the next signal location through both single track sections and passing sidings, and to employ a relay or other electro-responsive device at each end of such pair of line wires to afford double use of these line wires. It is proposed to employ a source of current at each end of such pair of line wires and to provide synchronously operated contacts on these electro-responsive devices near the end of each of the pair of line wires, for the purpose of at one instant connecting the relay at one end of these line wires to the source at the other end and for at the next instant connecting the relay at such other end to the source at such one end of said line wires. In accordance with the invention illustrated it is proposed to maintain the synchronously operated contacts in synchronism through the medium of a track circuit extending from one signal location to the next signal location adjacent such pair of line wires and at the same time employ this track circuit for manifesting the presence of a train in the section of track extending from one to the other of such signals, the signaling circuits being so organized that line circuit control is unnecessary when the track circuit adjacent such line wires is occupied by a train.

Another feature of the present invention resides in the employment of a plurality of codes on a track circuit which codes may manifest distinctive traffic conditions and at the same time operate contacts in synchronism for the purpose of alternately transmitting controls in opposite directions over the pair of line wires above mentioned and located adjacent the track circuit.

2

Another feature of the present invention resides in the employment of an inverse code sometimes called an "off code" for the purpose of transmitting additional information over a track circuit in the direction from the track relay end toward the track battery end thereof. Another feature of the present invention resides in the provision of signaling circuits whereby the presence of a train on one passing siding is manifested by the display of a caution signal at the next passing siding in advance of the train. This latter feature is particularly desirable where the single track section is so short that double braking distance is not available between two opposing intermediate signals along such single track section.

Other objects, purposes and characteristic features of the present invention will in part be described hereinafter and will in part be obvious from the accompanying drawings, in which:

Figs. 1A, 1B, 1C, 1D and 1E when laid end to end constitute one signaling system embodying the present invention;

Fig. 2 illustrates the positions that the contacts of the search-light signal assume under clear, caution and stop traffic conditions, respectively;

Figs. 3A, 3B, 3C, 3D, 3E, 3F, 3G and 3H illustrate the signal indications and their conditions of illumination when a train occupies various points along the trackway;

Figs. 4A, 4B, 4C, 4D and 4E illustrate a modified form of the present invention;

Figs. 5A, 5B, 5C, 5D, 5E, 5F, 5G, 5H and 5I illustrate the various signal indications for the system shown in Figs. 4A, 4B, 4C, 4D, and 4E with an east bound train occupying various points along the track;

Figs. 6A, 6B, 6C, 6D, 6E, 6F, 6G, 6H, 6I, 6J, and 6K illustrate the various signal indications and their conditions of illumination when a west bound train occupies various positions along the track; and

Figs. 7A, 7B, 7C, 7D, 7E, 7F, 7G, 7H, and 7I illustrate the various signal indications and their conditions of illumination when two oppositely moving trains make a meet on a passing siding.

Fig. 1 structure.—Referring to Figs. 1A to 1E, inclusive, the track rails 10 have been shown divided into sections by insulating joints 11 to insulate adjacent track sections from each other. The railway signaling system illustrated includes a passing side A, a passing siding B, a single track section C connecting the two passing sidings together and a portion of another single track section. The various signals have been designated S

with a suffix number to distinguish these signals from each other, the signals S10, S10A, S11, S12, S13, S14, S17, S18, S19, S19A, S20, S20A, S21 and S23 having been illustrated. Each of these signals may constitute a signal of either the semaphore type, the multiple unit light signal type, or the multiple aspect searchlight signal type, but for convenience only the search-light type signal has been illustrated in the drawings. This search-light type signal is preferably of a construction such as illustrated in the patent to Field, No. 2,097,785, dated November 2, 1937. The polar windings of these search-light type signals have been designated W with a suffix number corresponding to the suffix number of the signal itself. Each of these windings W is controlled by a polar neutral home-distant relay HD having a prefix number corresponding to the suffix number of the signal. Each of these home-distant relays is controlled by one or more of the following relays: A caution-clear signal repeater relay YGP, a clear signal repeater relay GP, a directional stick relay S, a track repeater relay FBP, an approach track repeater relay ATP and an approach home-distant relay AHD, each of these track relays being provided with a distinctive identifying number corresponding to the track circuit with which they are associated and each of the remaining relays being provided with a distinctive identifying number corresponding to the identifying number of the signal which the home-distant relay in question controls. The reference characters CT and CPR with a suitable suffix and the relay to which it is assigned designate suitable code creating apparatus for intermittently closing a contact. Where this letter CT or CPR has associated with it the number 75 signifies that the contact is closed approximately seventy-five times per minute, and where this letter CT or CPR has associated therewith the number 120 signifies that its associated contact intermittently closes one hundred and twenty times per minute. These code creating devices may be of any suitable construction and are preferably operated electrically and continuously. It is believed unnecessary to describe the circuits associated with all of the signals illustrated, and for convenience the circuits associated with the signal S12 and some of the circuits controlling the signal S17 only will be described, and like parts of remaining signal circuits will be assigned like reference characters having distinctive exponents, prefixes or suffixes.

Referring to Figs. 1B and 1C of the drawings, the signal S12 is a signal of the search-light type having a polarized mechanism controlled by the winding W12. This winding W12 is energized by current of normal polarity under normal clear traffic conditions, as illustrated. This energizing circuit extends from the terminal (+) of a suitable source of current through the polar contact 12¹² of the relay 12HD assuming its right-hand position, the front contact 13¹² of this same relay, the winding W12, the neutral contact 14¹², and the polar contact 15¹² assuming its right-hand position and to the other terminal (-) of this same source of current. This home-distant relay 12HD is under normal clear traffic conditions, as illustrated, energized to its right-hand polar position through the following circuit: beginning at the terminal (+) of a suitable source of current, front contact 17¹⁴ of the signal repeater relay 14YGP, front contact 18¹² of the track relay 12T, front contact 19¹² of the track repeater relay 12FBP, front contact 20¹² of the coding relay

12CPR, back contact 21¹³ of the opposing directional stick relay 13S, winding of the home-distant relay 12HD, front contact 22¹⁴ of the signal repeater relay 14YGP and to the other terminal (-) of said source of current. Under caution traffic conditions the home-distant relay 12HD is controlled through a circuit similar to the one just traced but is energized by current of negative polarity. This circuit includes the same contacts as the contacts just recited except that the contacts 17¹⁴ and 22¹⁴ of the signal repeater relay 14YGP assume their retracted position and except for the fact that the front contact 24¹⁴ of the directional stick relay 14S is included in series in this circuit. The coding relay 12CPR, as conventionally shown, is energized intermittently through a front contact 28 of suitable code creating apparatus 15CT at a code rate of 75 impulses per minute. It is thus seen that the home-distant relay 12HD cannot be energized to its left-hand polar position unless the directional stick relay for the next signal in advance assumes its energized position.

It is, of course, understood that the coding relay 12CPR is intermittently energized seventy-five times per minute and that when it assumes its energized position the track circuit extending from the signal S12 to the signal S14 is closed. This track circuit includes the track battery B12, the approach relay A12T, the coding contact 25¹² and the track relay 12T in series. This track relay 12T will of course be intermittently picked up at the rate of seventy-five times per minute in substantial synchronism with the coding relay 12CPR so long as the track circuit is not occupied by a train. The intermittent picking up of the track relay 12T through the medium of its front contact 26¹² intermittently applies energy to the slow dropping track repeater relay 12FBP so as to cause it to assume its energized position continuously and in the same manner this contact 26¹² as it intermittently assumes its retracted position will intermittently apply energy to the inverse track repeater relay 12FBP through the medium of front contact 27¹² of the code repeater relay 12FP, to cause this relay 12FBP to continuously assume its energized position. The track repeater relay 12FP is in fact an "on" pulse repeater relay whereas the track repeater relay 12FBP is an "off" pulse repeater relay which also checks the presence of "on" impulses and therefore constitutes a relay that can be up continuously only if the track relay 12T is intermittently picked up. The net result is that the track repeater relay 12FBP assumes its energized position only if the track circuit is intermittently energized.

The directional stick relay 12S is provided with a pick-up circuit including the front contact 30¹³ of the approach track repeater relay A13TP and a front contact 31¹² of the caution-clear signal repeater relay 12YGP. This directional stick relay 12S is also provided with two stick circuits, one including the back contact 31¹² of the signal repeater relay 12YGP, the other including the front contact 30¹³ of the approach track repeater relay A13TP, and both including the stick contact 32¹² of this directional stick relay 12S. The signal repeater relay 12YGP is normally energized through the back contact 30¹³ of the relay A13TP and the clear contact 33¹² of the search-light mechanism of signal S12, and under caution traffic conditions is energized in series through this same back contact 30¹³ and the contacts 33¹² and 34¹² of this signal S12 both assuming the left-hand caution position (see also Fig. 2). Atten-

tion is at this time directed to Fig. 2 which illustrates the positions assumed by the contacts 33 and 34 under clear, caution and stop traffic conditions, respectively.

The approach home relay 17AHD (see Fig. 1C) is controlled by the contacts 17¹³ and 22¹³ of the caution clear signal repeater relay 13YGP in exactly the same manner as the home-distant relay 17HD is controlled by the contacts 17¹⁴ and 22¹⁴ of the caution-clear signal repeating relay 14YGP and by the directional stick relays 13S and 14S and the track repeater relay 12FBP. It should, however, be noted that this approach home-distant relay 17AHD does not directly control a signal but does control the home-distant relay 17HD, which in turn controls signal S17. The normal clear circuit for the home-distant relay 17HD may be traced as follows: beginning at the terminal (+) of a suitable source of current, polar contact 36¹⁷ of the relay 17AHD assuming its right-hand position, front contact 37¹⁷ of this same relay, contact 20¹⁴ of the coder 15CT14, front contact 19¹⁷ of the track code repeater relay 14—17FBP, back contact 18^{14—17} of the track relay 14—17T, winding of the home-distant relay 17HD, front contact 38¹⁷ of the approach home-distant relay 17AHD, polar contact 39¹⁷ of the relay 17AHD assuming its right-hand position and to the other terminal (—) of said source of current.

Referring again to Fig. 1B of the drawings, as heretofore mentioned the directional stick relay 12S has a pick-up circuit including a front contact 30¹³ of an approach track code repeater relay A13TP. It may be pointed out that this relay A13TP is normally deenergized (track circuit unoccupied) because there is insufficient current flowing in the approach track relay A13T to pick it up when there is no train in the block. The presence of a train in the block will, however, cause intermittent picking up of the approach track relay A13T causing intermittent application of energy to the approach track repeater relay A13TP through the front contact 41¹³ of the approach code following track relay A13T. Since this approach track repeater relay A13TP is short circuited by a rectifier, as conventionally shown, it will not drop away during the periods of intermittent deenergization of the approach track relay A13T. In other words, the approach track repeater relay A13TP is continuously deenergized so long as the associated block is unoccupied but continuously assumes its energized position during occupancy of such block. At those locations where the directional stick relay is picked up by the dropping of a track repeater relay, instead of the picking up of an approach track repeater relay, the contact in the pick-up circuit for the stick relay has been designated 40 with an exponent corresponding to the track relay with which it is associated.

Each of the track switches SwE, SwEB and SwW is provided with a detector track circuit. The track relays for these detector track circuits have been designated DTE, DTEB and DTW, respectively. By referring to the detector track relay DTE (see Fig. 1A) it will be seen that in addition to the contact 40DE already mentioned this track relay is provided with front contacts 42DE, 43DE and 44DE. The front contact 42DE is included in the circuits for controlling the home relays 10HD and 13HD, respectively, and performs the same function in these circuits that the front contact 19¹³ of the track repeater relay 13FBP performs. In other words, the home relays 10HD

and 13HD cannot assume an energized position unless both the detector track circuit including the track relay DTE and the track circuit including the track relay 13T are unoccupied. In a similar manner the front contact 43DE is included in the energizing circuit for the home-distant relay 11HD, so that the home-distant relay 11HD cannot be picked up unless both the track circuit containing the track battery B¹¹ and the detector track circuit containing the detector track relays DTE and DTEB are both unoccupied. The other contact 44DE is included in series with the front contact 45¹³ of the track repeater relay 13FBP and these two contacts in series are capable of shunting the front contact 24¹⁰ of the directional stick relay 10S. These front contacts 44^{DEB} and 45²³ (see Fig. 1E) are effective to de-energize the home-distant relay 18HD (see Fig. 1D) when there is a west-bound train in the section extending from signal S20 to signal S23 (directional stick relay 20S deenergized and its contact 24²⁰ open) to cause the signal S18 to assume the stop position and the signal S14 to assume the caution position when a west-bound train passes the signal S23.

As heretofore pointed out the railway signaling systems such as shown in Figs. 1A-1E are provided with wayside signals of the search-light type such as disclosed in the Field patent above referred to. Each of these signals includes a spectacle having color screens permitting the emission of green, yellow and red light respectively, this light being emitted from an incandescent lamp. These lamps are normally deenergized and are energized only upon the approach of a train in the approach track sections unless the signal is at stop. These incandescent lamps have been designated L with a suffix corresponding to the signal with which they are associated and are each included in an energizing circuit containing an approach lighting contact 46 controlled by a back contact of a signal repeater relay, and for convenience all of these contacts have been designated 46 with an exponent corresponding to the signal repeating relay with which they are associated. These relays GP and YGP are signal repeating relays in that they cannot assume an energized position when the associated signal is at stop. They, however, also perform an approach lighting function in that they will also be de-energized when a train approaches the associated signal. The relay 12YGP is deenergized upon picking up of approach repeater track relay A13TP due to occupancy of the block extending from signal S10 to S12. Attention is directed to the fact that dropping of either the signal repeater relays 10YGP and 11GP will light all of the three signal lamps L10, L10A, and L11. This is resorted to so that a train standing on the passing siding (non-track circuited) will have its signal lighted under all adverse traffic conditions. In other words, these signal repeating relays GP and YGP at times, by dropping, reflect the approach of a train by lighting the signal and at other times manifest that the signal is at stop.

Obviously, the two ends of the passing siding include the usual track switches, which are presumably hand operated in the present system, and in order to manifest the position of these track switches in the various signaling circuits these track switches have been provided with switch-box or switch repeating contacts 48, 49 and 50 with an exponent corresponding to the track switch with which they are associated. The switch repeater contact 48^{swE} is included in the

energizing circuit for the magnet winding W_{10} of the signal S_{10} , and similarly the contact 49^{SWE} is included in series with the winding W_{10A} for the starting signal S_{10A} , when the track switch SwE assumes respective the normal and the reverse position. The contact 50^{SWE} is included in series in the energizing circuit of the home-distant relay $11HD$ so that this relay $11HD$ is assured of deenergization to reflect danger traffic conditions when the switch SwE is in the take-siding position. The contacts for the remaining track switches have been designated by the same reference characters having distinctive exponents corresponding to the track switches with which they are associated.

It will be observed that the directional stick relay $10S$ is provided with two pick-up circuits. The one including the front contact 31^{10} of the clear-caution signal repeating relay $10YGP$ and the other including the front contact 31^{10A} of the clear-caution signal repeating relay $10AYGP$ and both including the back contact 40DE of the detector track relay DTE . It will also be seen that one stick circuit for relay $10S$ includes back contact 40DE and the stick contact 32^{10} and that another stick circuit includes the back contacts 40^{13} , 31^{10A} and 31^{10} of relays $13FBP$, $10YGP$ and $10AYGP$ respectively. This circuit construction is resorted to in order to afford a pick-up circuit for directional stick relay $10S$ irrespective of whether the train entering the west end of the single track section illustrated moves off of the main track or off of the side track of the passing siding A. It will be noted that only one of signal repeating relays $10YGP$ or $10AYGP$ can be energized at a time and for this reason front contacts 31^{10} and 31^{10A} have been provided in multiple for picking up the directional stick relay $10S$. The directional stick relays $19S$ and $20S$ are similarly controlled by contacts identified by like reference characters having distinctive exponents.

Under normal conditions of the railway signaling system illustrated the track switches SwE , $SwEB$ and SwW shown in Figs. 1A, 1D and 1E all assume their normal main track position. Attention is directed to the fact that the detector track circuits associated with these track switches are of the non-coded type, that is, the track relays are continuously energized so long as the detector track circuits are not occupied and assume their deenergized positions so long as such detector track circuits are occupied. Each of the remaining track circuits illustrated in Figs. 1A to 1E are coded at the 75 impulse per minute code rate and during unoccupancy the track relays of these track circuits pick up and drop away seventy-five times during each minute of unoccupancy. It will also be noted that all of the coded track circuits except the track circuits between signals S_{14} and S_{17} and between signals S_{19} and S_{20} is provided with an approach track relay designated AT with a number between these letters each corresponding to the prefix of the track relay with which it is connected in series. These approach track relays are normally deenergized and are intermittently energized at the 75 impulse per minute rate during occupancy of the track circuit in which they are included. These approach track relays are series relays and require a larger than normal track circuit current to pick them up. It will be seen that these approach track relays are only used for controlling signal repeater relays also controlled by signal mechanism contacts and directional stick relays, and when so used conform to the principle of the

normally closed circuit. It is considered perfectly safe to control the picking up of a directional stick relay by a contact of an approach relay although an approach relay is not considered reliable for directly controlling a signal. This is true by reason of the fact that it is a normally deenergized relay and functions on the open circuit principle and further because its failure to pick up results in a danger aspect instead of a caution aspect.

As just pointed out the track circuits through the single track section are coded at the 75 impulse per minute code rate, but this is not done for the purpose of transmitting a special control over the track circuit itself, but is used primarily to provide a way of operating contacts at both ends of the track circuit intermittently and in synchronism. In the system of Fig. 4 it is, however, used to transmit special controls. These contacts have been designated 18 and 20 in the drawings. The contact 20 is a contact on a coding relay which codes the track circuit, and the contact 18 is the contact on the track relay at the opposite end of the track circuit which, of course, closely follows the operation of the coding contact 25 located at the source end of the track circuit. It will readily be seen that with the contacts 18^{13} (see Fig. 1A) and 20^{13} (see Fig. 1B) when both energized allow current to flow from right to left through this circuit to pick up the home-distant relay $10HD$ from a source at the east end of the line circuit, and that if these contacts 18^{13} and 20^{13} are both deenergized they allow current to flow from a source at the west end to pick up the home-distant relay $13HD$. This alternate use of the two line wires at a seventy-five times per minute rate is resorted to for controlling the home and distant relays $10HD$ and $13HD$, and due to their slow-dropping characteristics causes these relays $10HD$ and $13HD$ during clear or caution traffic conditions to be maintained continuously energized. In other words, the line circuit performs a double function in that the contacts 18 and 20 allow the time of use of this line circuit to be allotted alternately for the alternate energization of these relays $10HD$ and $13HD$. What has been said in regard to the home-distant relays $10HD$ and $13HD$ is also true of all of the other home-distant relays and approach home-distant relays of Figs. 1A-1E as well as of the mechanisms M of Figs. 4A-4E.

Fig. 1 operation.—Let us now assume that there is an east-bound train moving on the main track of the passing siding A (see Figs. 1A and 3A). The presence of this train will open the circuit for the home-distant relay $11HD$ at a contact not shown in Fig. 1A but shown in Fig. 1D and designated 19^{21} of track repeater relay $21FBP$. With the home-distant relay $11HD$ deenergized the signal S_{11} is put to stop, as shown by the letter "R" in Fig. 3A, because the circuit for the control of its winding W_{11} is open at front contacts 13^{11} and 14^{11} of the relay $11HD$. With the signal S_{11} assuming its stop position its contacts 33^{11} and 34^{11} will assume a stop position as illustrated in the lowermost sketch of Fig. 2 of the drawings, and when in such position the circuit for the signal repeater relay $11GP$ is broken, thereby causing this relay $11GP$ to assume its retracted position and operate its pole-changer contacts 17^{11} and 22^{11} to the reverse position, in which position the current through the winding of the home-distant relay $13HD$ is reversed so that the polar contacts 12^{13} and 15^{13} of this home-distant relay $13HD$ assume the left-

hand position to cause the current flowing in the winding W13 of this signal S13 to be reversed thereby operating the signal S13 to caution position in which it emits a yellow signal beam and operates the contacts 33¹³ and 34¹³ to the left-hand or caution position (see Fig. 2) in which position the clear-caution relay 13YGP remains energized as before. In other words, movement of the signal S11 to the stop position causes the signal S13 to assume the caution position, but the next signal in the rear, namely, signal S17 remains in its clear position (see Fig. 3A). In other words, a train whether east-bound or west-bound standing on the main track of the passing siding A (see Fig. 1A) is protected against a west-bound train moving in the single track section by a stop signal and a caution signal next in the rear thereof.

The dropping of the signal repeating relay 11GP, however, performs another function, namely, the closing of its approach lighting back contact 46¹¹, which results in the illumination of the lamps L10, L10A and L11. These three lamps are controlled in multiple because it is desired to illuminate the lamp L10A each time either the lamp L10 or L11 is energized. It may be pointed out here that the lamp L10A is not energized with a train on the side track of the passing siding unless the associated track switch is in its take-siding position. With the track switch SwE in the take-siding position the switch box contacts 48SwE and 50SwE are both open placing the signals S10 and S11 in the stop position but allowing signal S10A to reflect traffic conditions ahead and causing deenergization of the signal repeater relays 10YGP and 11GP, which in turn cause the approach lighting contacts 46¹⁰ and 46¹¹ to be closed to approach light not only signal S10A but also signals S10 and S11.

Let us now assume that the east-bound train on the main track of the passing siding A (see Fig. 1A) advances past the clear signal S10 as shown in Fig. 3B. The presence of this train on the detector track circuit containing track relay DTE (see Fig. 1A) causes this detector track relay DTE to assume its deenergized position. Since this detector track relay DTE has a front contact 42DE included in the energizing circuit of the home-distant relay 13HD this home-distant relay 13HD is deenergized, thereby deenergizing the winding W13 of the signal S13 and operating this signal S13 to its stop position. Movement of the signal S13 to the stop position causes its contacts 33¹³ and 34¹³ to assume their left-hand and their right-hand positions, respectively (see lowermost sketch of Fig. 2), thereby opening the circuit for the signal repeater relay 13YGP causing deenergization of this relay. The dropping of the signal repeater relay 13YGP at its back contact 46¹³ closes an energizing circuit for the lamp L13 for the signal S13, so that this signal S13 will actually emit a red beam signifying danger traffic conditions to an opposing train. Furthermore, the dropping of the signal repeater relay 13YGP causes operation of the pole-changer contacts 17¹³, 22¹³ as a result of which the energizing circuit for the approach home-distant relay 17AHD (see Fig. 1C) is broken because with the contact 22¹³ of the signal repeater relay 13YGP in its retracted position the circuit for this approach home-distant relay 17AHD is open at front contact 24¹³ of the directional stick relay 13S, this directional stick relay only assuming its picked-up position in the event there is a west-bound train moving in the

block between signals S13 and S11. With the approach home-distant relay 17AHD now deenergized and its front contacts 31¹⁷ and 38¹⁷ open the energizing circuit for the home-distant relay 17HD is broken so that this relay 17HD assumes its retracted position. The dropping of this home-distant relay 17HD breaks the energizing circuit for the winding W17 for the signal S17 at its front contacts 13¹⁷ and 14¹⁷, thereby placing this signal S17 in its stop position. With the contacts 33¹⁷ and 34¹⁷ of the signal mechanism of signal S17 assuming the stop position (see Fig. 2) the caution-clear signal repeater relay 17YGP (see Fig. 1C) also assumes its retracted position and closes the signal lighting back contact 46¹⁷ for the lamp L17 of the signal S17. Furthermore, dropping of the signal repeater relay 17YGP causes pole changing of its contacts 17¹⁷ and 22¹⁷ and since the front contact 24¹⁷ of the directional stick relay 17S is open the energizing circuit for the home-distant relay 19HD is broken, thereby causing deenergization of the winding W19 for the signal S19 resulting in the placing of the starting or head block signal S19 in the stop position. In this connection it should be noted that the energizing circuit for the winding W19 of the signal S19 includes a switch repeating contact 48^{SwW} and that if the track switch SwW assumed its take-siding position this contact 48^{SwW} would be opened but in this case the contact 49^{SwW} would be closed as a result of which the signal S19A instead of signal S19 would have been controlled in accordance with traffic conditions in advance. Movement of the signal S19 to the stop position causes the contacts 33¹⁹ and 34¹⁹ within the signal mechanism to assume the stop position as illustrated in the lowermost sketch in Fig. 2 and thereby cause the caution-clear repeater relay 19YGP to assume its retracted position. With the relay 19YGP in its retracted position the approach lighting contact 46¹⁹ is closed lighting up the lamps L18, L19, and L19A. Also, with the signal repeating relay 19YGP in its retracted position its pole-changer contacts 17¹⁹ and 22¹⁹ reverse the polarity of the current applied to the home-distant relay 21HD (see Fig. 1E). This is true even though the directional stick relay 19S is in its normal retracted position. This is true because its front contact 24¹⁹ of this stick relay is shunted by a shunt circuit including the front contact 44^{DW} of the detector track relay DTW included in series with the front contact 45¹⁹ of the track repeater relay 19FBP. In other words, the dropping of the signal repeater relay 19YGP causes pole changing of the circuit for the home-distant relay 21HD to place the signal S21 in its caution position so long as neither the track circuit containing the track relay 19T or the detector track circuit containing the detector track relay DTW (see Fig. 1D) become occupied. Should, however, the train in question pass the opposing signal S17 the signal S21 would be moved to its stop position by reason of opening of the front contact 45¹⁹ of the track repeater relay 19FBP (contact 24¹⁹ of relay 19S being open). With the signal S21 now assuming its caution position because the home-distant relay 21HD has been operated to its left-hand polar position (the train under consideration still occupying the position illustrated in Fig. 3B) and has pole changed the current flow in the winding W21, causes the signal S21 to assume the caution position. This operation of the mechanism of the signal S21 to its caution position, in which both of its contacts 33²¹ and 34²¹ assume their

left-hand position as illustrated in Fig. 2, causes the energizing circuit for the clear signal repeater relay 21GP to be deenergized, which results in operation of its pole-changer contacts 17²¹ and 22²¹ to the reverse position, and in turn will cause the signal S23 to assume the caution position. In other words, the movement of the east-bound train past the signal S10 (see Figs. 1A and 3B) causes a tumble down of stop signals to take place throughout the entire single track section resulting in the placing at stop of all of the opposing or west-bound signals S11, S13, S17 and S19 and further results in putting the signals S21 and S23 in the caution position.

Another function that takes place as the east-bound train passes the signal S10 resides in the picking up of the directional stick relay 10S. This is accomplished by the closing of the pick-up circuit including the back contact 40DE of the detector relay and including the back contact 31^{10A} or the slow-dropping signal repeater relay 10AYGP, the front contact 31¹⁰ of the slow-dropping signal repeater relay 10YGP and the winding for this stick relay 10S. With the stick relay 10S once energized it is stuck up through a stick circuit including the back contact 40DE of the detector track relay DTE and the stick contact 32¹⁰ in series.

As the east-bound train advances past the opposing signal S11 (see Fig. 3C) it results in continuous deenergization of the track relay 13T, which in turn results in continued deenergization of the home-distant relay 10HD which was formerly deenergized by reason of open contact 42DE of the detector track relay DTE included in series in its energizing circuit. With the track relay 13T continuously deenergized the track repeater relays 13FP and 13FBP are continuously deenergized. With the track repeater relay 13FBP in its retracted position and with its back contact 40¹³ closed a supplemental stick circuit for the directional stick relay 10S is closed which stick circuit includes the back contact 49¹³ of the track repeater relay 13FBP, the back contacts 31¹⁰ and 31^{10A} of the signal repeater relays 10YGP and 10AYGP in series, and the stick contact 32¹⁰ of this directional stick relay 10S. Although the signal S12 had its mechanism in the clear position under the assumed traffic condition under consideration as illustrated in Fig. 3B, this signal was then a dark signal, its associated approach lighting contact 46¹² of relay 12YGP being open. With the train now advanced past opposing signal S11 to a position as illustrated in Fig. 3C the approach track relay A13T is intermittently picked up to hold up repeater track relay A13TP continuously. This results by opening of its back contact 30¹³ in dropping of relay 12YGP and by closing of back contact 46¹² in the lighting of signal lamp L12.

As the rear end of the train passes off of the detector track circuit containing track relay DTE (see Figs. 1 and 3C) the front contact 44DE of this relay is reclosed, so that this particular circuit for the home-distant relay next in the rear (corresponding to relay 18HD of Fig. 1D) is closed at this point. This is, however, of no particular importance at this time because with the directional stick relay 10S in its energized position its front closed contact 24¹⁰ applies caution energy through a branch circuit in multiple with this front contact 44DE to the home-distant relay next in the rear, which is not shown in Fig. 1A but has been designated 18HD in Fig. 1D of the drawings.

As the east-bound train under consideration continues its movement between the signals S11 and S12 (see Fig. 3C) the directional stick relay 10S will remain stuck up through the supplemental stick circuit heretofore traced, the original stick circuit through back contact 40DE having been opened. Movement of the east-bound train between the signals S11 and S12 as above pointed out results in the intermittent picking up of the approach relay A13T which in turn results in the repeater approach relay A13TP assuming its energized position continuously. The front contact 30¹³ of the approach relay A13TP now closes a pick-up circuit for the directional stick relay 12S. This directional stick relay 12S is then stuck up through a stick circuit heretofore traced in connection with the directional stick relay 10S. Also, the continuous picked-up condition of approach repeater track relay A13TP opens its back contact 39¹³ and drops the caution clear signal repeater relay 12YGP and the closure of its back contact 46¹² closes an energizing circuit for the lamp L12. As the east-bound train now passes the signal S12 (see Fig. 3D) it will result in the continuous picking up of the approach repeater relay A12TP. Since, however, the signal S13 assumed its stop position, in view of the tumble-down which took place when the train passing signal S10, and its repeater relay 13YGP assumed its retracted position the directional stick relay 13S is not picked up. The presence of this east-bound train in the track section between the signals S12 and S14 (see Fig. 3D), however, results in continuous deenergization of the track relay 12T which in turn results in continuous deenergization of the track repeater relays 12FP and 12FBP, so that the front contact 19¹² of the track repeater relay 12FBP is opened thereby resulting in the continuous deenergization of the home-distant relay 12HD which in turn results in putting the signal S12 in its stop position all for reasons heretofore pointed out. Also, with the track repeater relay 12FBP continuously deenergized the opening of its front contact 40¹² and deenergization of the caution-clear relay 14YGP causes the approach lighting contact 46¹⁴ in the circuit for lamp L14 to be closed and the signal S14 to become lighted as shown in Fig. 3D.

With the signal S12 in the stop position its caution-clear repeater relay 12YGP is deenergized so that its approach lighting contact 46¹² is closed to light the signal lamp L12 so long as the signal S12 remains at stop and irrespective of the position assumed by the contact 30¹³ of track repeater relay A13TP. This dropping of the clear-caution signal repeater relay 12YGP at its back contact 31¹² also closes a supplemental stick circuit for the directional stick relay 12S. As soon as the rear end of the train passes the signal S12 (see Fig. 3D) the track relay 13T will again intermittently respond to the coded current applied to the track circuit in which it is included by the contact 25¹³ of the coding relay 13CPR. Intermittent picking up of the track relay 13T causes the track repeater relays 13FP and 13FBP to be held up continuously. The picking up of this latter track repeater relay 13FBP by the closing of its contact 19¹³ allows caution current to flow to the home-distant relay 10HD through a circuit including the front contact 24¹² of directional stick relay 12S, the front contact 19¹³ of relay 13FBP and the front contact 42DE of the detector track relay DTE, as a result of which the signal S10 may assume the caution position. This

caution signal is, however, a dark signal (see Fig. 3D) unless either the track switch S_{wE} is in the reverse position or there is a train approaching the signal S_{10} . The signal S_{13} (see Fig. 3D), although there is no traffic in advance thereof, will not assume its clear position because the energizing circuit for the home-distant relay $13HD$ is still open at the back contact 21^{12} of the directional stick relay $12S$.

The re-energization of the track repeater relay $13FBP$ to its continuous picked-up condition opens the back contact 40^{13} of this relay, thereby opening the supplemental stick circuit for the directional stick relay $10S$ heretofore traced. This causes dropping of this directional stick relay $10S$ and the closing of its back contact 21^{10} included in series in the energizing circuit of the home-distant relay $10HD$, so that relay $10HD$ picks up. The picking up of this home-distant relay $10HD$ causes the signal S_{11} to assume its clear position as a result of which its clear signal repeater relay $11GP$ is energized to re-apply current of normal polarity to the energizing circuit for the home-distant relay $13HD$. This latter relay $13HD$ will, however, not yet pick up because its circuit is still open at the back contact 21^{12} of the directional stick relay $12S$. The picking up of the track repeater relay $13FBP$ by the closing of its contact 19^{13} closes the energizing circuit for the home-distant relay $10HD$, and this home-distant relay $10HD$ will be energized to its left-hand polar position because the pole-changer contacts 17^{12} and 22^{12} of the signal repeater relay $12YGP$ still assume their retracted caution position because the signal S_{12} still assumes its stop position. With these contacts 17^{12} and 22^{12} in their retracted position and with the directional stick relay $12S$ still in its attracted position caution energy is applied to the home-distant relay $10HD$ resulting in the operation of its spectacle to a caution position but a caution signal will not be displayed because its lamp L_{10} is deenergized. The relays $10YGP$ and $11GP$ are now both in their picked-up positions.

Let us now assume that the east-bound train, which now occupies the track section between the signals S_{12} and S_{14} , advances past the signal S_{14} , it being of course understood that the previous presence of the train in the section between signals S_{12} and S_{14} resulted in the dropping of the track repeater relay $12FBP$ and in the picking up of the directional stick relay $14S$. Also, the dropping of this track repeater relay $12FBP$ by opening of its front contact 40^{12} and the dropping of relay $14YGP$ caused the signal lamp L_{14} to be lighted due to closing of approach contact 46^{14} . As the east-bound train now passes the signal S_{14} its presence will cause the continuous deenergization of the track relay $14-17T$ as the result of which the track repeater relays $14-17FP$ and $14-17FBP$ are both continuously deenergized. The dropping of this latter track repeater relay by the opening of its contact $19^{14}-17$ causes deenergization of the home-distant relay $14HD$ (relay $17HD$ having been earlier deenergized) resulting in deenergization of the winding W_{14} of the signal S_{14} and resulting in the movement of the signal mechanism of the signal S_{14} to the stop position. With the contact 33^{14} and 34^{14} assuming the stop position, as shown in Fig. 2, the caution-green signal repeater relay $14YGP$ for the signal S_{14} is maintained deenergized, and its approach lighting contact 46^{14} remains closed causing the signal lamp L_{14} to remain lighted. As the rear end of the train passes the signal S_{14}

(see Fig. 3E) the track relay $12T$ will again be intermittently picked up, resulting in the permanent picking up of the track repeater relays $12FP$ and $12FBP$. The picking up of the track repeater relay $12FBP$ at its front contact 19^{12} recloses the energizing circuit for the home-distant relay $12HD$. Since, however, the signal repeater relay $14YGP$ is still in its retracted position and since its directional stick relay $14S$ is still stuck up caution energy is applied to this home-distant relay $12HD$ resulting in the operation of the signal S_{12} to its caution position, but will not display a caution indication because its lamp L_{12} is not lighted. With the signal S_{12} now assuming its caution position its signal repeater relay $12YGP$ assumes its energized position, thereby extinguishing its signal lamp L_{12} and dropping the directional stick relay $12S$ and returning its pole-changer contacts 17^{12} and 22^{12} back to their normal clear position in which position current of normal polarity is applied to the home-distant relay $10HD$ resulting in the clearing of the signal S_{10} with the exception of lighting of lamp L_{10} , it remaining a dark signal. Let us now assume that the east-bound train passes the opposing signal S_{17} . This results in the intermittent picking up of the approach track relay $A19T$ and in the continuous picking up of its repeater relay $A19TP$. The picking up of contact 30^{19} of this relay $A19TP$ maintains the signal repeater relay $17YGP$ in its deenergized position even though the mechanism of the signal S_{17} were operated to its clear position when the rear end of this train completely passed the signal S_{17} . The mechanism of the signal S_{17} , however, remains in its stop position (see Fig. 3F) because the directional stick relay $14S$ is still held stuck up by its holding circuit through back contact 31^{14} of relay $14YGP$, this relay $14YGP$ being held deenergized by signal S_{14} at stop which is held at stop because the presence of the train in the section between signals S_{17} and S_{18} holds approach home relay $14AHD$ deenergized which in turn holds home relay $14HD$ deenergized. The energized directional stick relay $14S$ at its back contact 21^{14} holds approach home relay $17AHD$ deenergized which in turn holds the home relay $17HD$ deenergized which holds the signal S_{17} in its stop signal-lamp-lighted position. Furthermore, the presence of the train in the track section between the signals S_{17} and S_{18} results in the continuous deenergization of the track relay $19T$ and in the deenergization of its repeater track relays $19FP$ and $19FBP$. The dropping of the track repeater relay $19FBP$ by the opening of its contact 45^{19} opens the shunt circuit, comprising the contacts 44^{DW} and 45^{19} in series and extending around the open front contact 24^{19} of the directional stick relay $19S$, thereby causing the home-distant relay $21HD$ for the signal S_{21} to assume its retracted position. As heretofore pointed out this signal S_{21} , controlled by this home-distant relay $21HD$ heretofore assumed a caution position upon the entrance of the east-bound train into the signal track section. The dropping of the home-distant relay $21HD$ due to the presence of the east-bound train in the track section between signals S_{17} and S_{18} now results in the operation of the signal S_{21} to its stop position. This change in the position of the signal S_{21} , known in signal parlance as the siding overlap control, however does not change the indicating condition of the signal S_{23} , this signal already having been operated to the caution position in response to the dropping of signal repeating relay $21GP$ due to

the former operation of the signal S21 to the caution position. The movement of the train under consideration out of the section between signals S14 and S17 does not in any way affect the signal S14 because the presence of a train in any part of the stretch from signal S14 to signal S18 holds the signal S14 at stop. Also, as already explained, the signal S14 at stop due to an east-bound train holds the signal S17 at stop.

Movement of the east-bound train past the signal S18 causes the operation of the signal S12 to the stop position by reason of deenergization of the detector track relay DTW which has a front contact 43^{DW} included in the energizing circuit of the home-distant relay 18HD. As the east-bound train proceeds past the opposing signal S19 the energizing circuit for this same home relay 18HD is broken at another point, namely, at the front contact 19²¹ of the track repeater relay 21FBP. Not only does this opening of the contact 19²¹ interrupt the energizing circuit for the home-distant relay 18HD, but it also breaks at another point the home-distant relay 21HD. As the rear end of the train passes the signal S18 (see Fig. 3G) the approach repeater relay A19TP drops to reclose its back contact 30¹⁹ thereby picking up the relay 17YGP and thereby extinguishing the lamp L17. It should be understood that the mechanism of the signal S17 will be returned to its clear position where the signal S14 is operated to the caution position, will drop its directional stick relay 14S and close the energizing circuit for the approach home relay 17AHD at the back contact 21¹⁴. As the train under consideration now entirely passes the signal S19 (Fig. 3H) the picking up of detector track relay DTW to reclose its front contact 42^{DW} included in the circuit of home-distant relay 14AHD, which by picking up, re-energizes relay 14HD to its caution position as already pointed out. This results in returning the mechanism of signal S14 to caution to pick up relay 14YGP to leave signal S14 a dark signal. The train under consideration now assumes the same position at passing siding B that it assumed at passing siding (see Fig. 3A) when this train operation was first considered.

From the above discussion of train movement it is readily seen that the signaling system of Figs. 1A-1E of the present invention performs all of the functions heretofore performed by absolute-permissive-block signaling systems and additional functions, and performs these functions by the employment of only two line wires which transmit controls in opposite directions therein intermittently at a code rate of 75 reversals of use of these line wires during each minute interval. It is seen that the entrance of a train into the single track section at the west end (see Fig. 1A) will cause all of the opposing signals in the single track section to assume their stop position and will cause the next two opposing signals in the rear of the most remote signal at stop to assume the caution position, giving what is well known in the art as the double caution control through the passing siding. All of these functions are performed without additional line wires above the two line wires heretofore mentioned. It is also seen that not only does the signaling system properly control the opposing signals, but it also allows train movements following each other through the single track section in the usual permissive manner of displaying one stop signal directly back of a train and one caution signal to the rear of such stop signal behind each train moving through the single track section.

Let us now assume that there is a train standing on the side track of the passing siding A ready to accept the signal S10A. Since this side track is not track circuited the presence of this train is not manifested anywhere else on the signaling system. Also the signal directly ahead of the train, namely, the signal S10A, assumes the stop position with its lamp L10A deenergized, because the energizing circuit for its signal mechanism including the winding W10A is open at the switch repeating contact 49SwE. Both of the signal repeating relays 10YGP and 10AYGP are energized under this condition. If this east-bound train on the side track of passing siding A has received a train order to proceed into the single track section, the brakeman will operate the switch SwE to its take-siding position by hand. If the single track section is at this time unoccupied the signal S10A will assume its clear position as soon as the track switch has been operated to the take-siding position resulting in the closure of the contact 49SwE. This will result in putting the signal S10 to stop which causes the relay 10YGP to be deenergized to cause the signal lamps L10, L10A and L11 to be energized through back contact 46¹⁰ of relay 10YGP. The signal S10A now informs the engineer of the train under consideration of traffic conditions in advance. This operation of the track switch SwE to the take-siding position and the clearing of signal S10A also results in the closure of an energizing circuit for the signal repeater relay 10AYGP.

The east-bound train under consideration may now pass the signal S10A and also the opposing signal S11. As it passes signal S10A it drops the detector track relay DTE which through its back contact 40DE and contact 31^{10A} of relay 10AYGP closes a pick-up circuit for stick relay 10S. The closure of front contact 24¹⁰ of this directional stick relay 10S allows the signal in the rear to indicate caution through back contacts 17¹⁰ and 22¹⁰ of relay 10YGP. The picking up of directional stick relay 10S also by opening of its back contact 21¹⁰ places signal S11 in its stop position, which places the signal S13 at caution for obvious reasons. As this train has fully entered the single track section the brakeman may return the track switch SwE to its normal main-track position. This operation of the track switch SwE back to its normal main-track position results in the opening of the switch repeating contact 49SwE. This will, however, not result in the dropping of the directional stick relay 10S even though the back contact 40DE in one stick circuit is open, because there is a supplemental stick circuit for this directional stick relay 10S, which supplemental stick circuit includes the back contact 40¹³ of the now deenergized track repeater relay 13FBP, and includes the back contacts 31¹⁰ and 31^{10A} of the signal repeater relays 10YGP and 10AYGP and the stick contact 32¹⁰ of the directional stick relay 10S. In this connection it may be pointed out that the return of the track switch SwE to its normal position not only returns the signal S10A to its stop position, but it also left the signal S10 in its deenergized stop position because the home-distant relay 10HD is now deenergized because its energizing circuit is broken at the front contact 19¹³ of the track repeater relay 13FBP. The movement of the train under consideration through the single track section is otherwise in all respects the same as that heretofore described and need not be further considered at this time.

The system shown in Figs. 1A-1E, as apparent from the foregoing description, thus provides all

of the functions necessary in systems of the absolute-permissive-block type and accomplishes them over only two line wires extending the full length of the system. In addition to these features of the system very unusual approach lighting functions are provided. This so-called approach lighting also provides for the lighting of all signals at stop, with the exception of the starting signal governing movement of traffic off of the side track of the passing siding, irrespective of the approach of a train. This latter feature is of considerable help to track maintenance men in that the small cars they employ are not capable of causing the usual approach lighting because they are of insufficient weight, and also because their wheels may be insulated from the axle, to manifest their presence by shunting of the track circuit. Another feature is that opposing signals in the single track section are not cleared up when the train has passed them in an opposing direction. This feature is of particular advantage in that it prevents a train making an unauthorized back-up move in a single track section especially at speed. Also, the three signals associated with each track switch illustrated are all lighted up in consonance and are lighted when either the main track starting signal or an entering signal to the passing siding is at stop, that is, are lighted for both an approaching or a receding train.

Fig. 4 structure.—Figs. 4A, 4B, 4C, 4D and 4E when laid end to end in that order constitute a modified system of absolute-permissive-block signaling embodying the present invention. In this modified system there is less than double braking distance between the intermediate signals S4 and S3 and for this reason the circuits involved perform special functions to safeguard trains in spite of the lack of double braking distance between these signals. Without this safeguard the simultaneous entrance of trains at speed into opposite ends of the single track section might result in the two trains arriving at the intermediate signals almost simultaneously with both of their signals in the stop position which will, of course, leave inadequate braking distance for the two trains between these trains. It will be observed that in Fig. 1 there were provided two intermediate signals for each direction of traffic in the single track section, whereas in the Fig. 4 structure only one such intermediate signal for each direction of traffic is provided.

In this modified construction (Figs. 4A-4E) has been illustrated the east end of a passing siding A and the entire passing siding B as well as a single track section connecting these passing sidings, together with the necessary circuits and apparatus to afford proper signaling protection on the system, which system in addition to allowing the usual signaling protection for trains following each other (known as permissive signaling) as through the single track section also provides absolute signaling by blocking the entrance of trains moving in opposite directions against entrance into the single track section at the same time. In this system the starting signals at the west end (left-hand end) of the single track section and used for governing the movement of traffic into the single track section from that end known as stop-and-stay signals have been designated S2 and S2A (see Fig. 4A) and similar signals at the east end of the passing siding B have been designated S8 and S8A. The starting signals for governing the west-bound traffic through the single track section have been designated S5

and S5A. The remaining signals have been designated S1, S4, S3, S6, S9, S10B, S11B. As already pointed out in connection with the Fig. 1 system these signals may be of any suitable construction such as semaphore signals, multiple unit light signals, or signals of the search-light type, but for convenience signals of the search-light type have been illustrated. The search-light type signals illustrated in Figs. 4A-4E are of a modified construction as compared with the search-light type signals illustrated in Figs. 1A-1E. The signals illustrated in Figs. 4A-4E are of a construction as illustrated in the prior application of Field, Ser. No. 361,060, filed October 14, 1940, and more particularly is the signal illustrated in Figs. 1 to 17 with the elements interconnected with a full-wave rectifier as shown in Figs. 20, 21, 22 or 23 of said prior application. It is readily seen that the caution or home magnet of these signal mechanisms has retained characteristics and will not drop its armature upon pole changing of the energizing circuit.

Stating it rather briefly the mechanism of this search-light type signal, which has been designated M together with a suffix corresponding to the suffix number of the signal in which it is included, employs two electro-magnets or relays connected in series. These electro-magnets may conveniently be called the caution or home magnet HG and the clear or distant magnet DG. Of these magnets the home magnet HG is a neutral magnet which will pick up in response to direct current of either polarity, whereas the distant magnet DG is a polar magnet which will only pick up if the direct current is of normal polarity (presumably of positive polarity) and will then pick up only if the home magnet (neutral magnet) has already assumed its energized or attracted position. In other words, these magnets are connected in series and are under normal clear traffic conditions energized by current of normal polarity which causes the armatures of both of these magnets HG and DG to assume their attracted position but under caution traffic conditions, when these magnets are energized in series by current of reverse polarity, only the home magnet HG assumes its attracted position, the distant magnet DG assuming its retracted position. It will be observed that the home magnet HG in addition to operating the usual spectacle also operates suitable contacts, say, for instance, the contacts 17², 22², 31² and 46² associated with the mechanism M2 of the signal S2 (see Fig. 4A) and that in certain instances the distant magnet DG is also provided with contacts, as, for instance, the contacts 17¹ and 22¹ of the mechanism M1 associated with the signal S1 (see Fig. 4A). It should be kept in mind that the contacts associated with the distant magnet DG are only in their attracted position under clear traffic conditions, namely, when the signal in which the mechanism is included is energized by current of either polarity, whereas the contacts operated by the home magnet HG assume their attracted position under both the clear (green) and the caution (yellow) position of the signal spectacle, that is, pick up in response to current of either polarity. This must be kept in mind in studying the signaling system illustrated in Figs. 4A-4E.

By comparing Figs. 1A-1E with Figs. 4A-4E it will be observed that two directional stick relays are employed at the end of each passing siding in Fig. 4, whereas only one such directional stick relay is employed at the end of each passing sid-

ing in Fig. 1. These additional stick relays are necessary in order to transmit the special controls that must be transmitted in a system of absolute-permissive-block signaling which has only two intermediate signals and in which these signals are spaced less than double braking distance. These additional stick relays as well as the other stick relays illustrated in Figs. 4A-4E are substantially the same as those illustrated in Figs. 1A-1E and for this reason like contacts have been designated by like reference characters employing distinctive exponents. As already pointed out in connection with the system illustrated in Figs. 1A-1E the directional stick relay associated with a starting or head-block signal, such as stick relay 10S of Fig. 1A and stick relay 2S of Fig. 4A are provided with a pick-up circuit which is closed if either of the two head-block signals are at proceed when the detector track becomes occupied.

The directional stick relay associated with the entering signal (signal governing entrance to passing siding) such as stick relay 1S, for instance (see Fig. 4A) is provided with control circuits which are in part at least dependent upon the position assumed by the track switch with which the signal S1 is associated. This track switch repeating contact has been designated 52^{SW}E in Fig. 4A of the drawings and is provided to prevent the picking up of this directional stick relay 1S under any and all conditions of traffic when the track switch S^WE is in the take-siding position. This precaution is resorted to by reason of the fact that if this contact 52^{SW}E were not provided the movement of a train into the side track of the passing siding would pick up the directional stick relay 1S and if in the meantime an opposing train entered the main track of this same passing siding this opposing train could and would hold this directional stick relay 1S energized under a condition when it should not be energized. The directional stick relays for the two ends of the passing siding B are controlled in the same way as the stick relays of the east end of the passing siding A and for this reason the contacts in their control circuits have been designated by like reference characters having distinctive exponents.

In order to carry out the necessary controls in the system illustrated in Figs. 4A-4E two features of track circuit control are employed in the Fig. 4 construction that are not employed in the Fig. 1 construction. These features are (1) the employment of inverse codes whereby a traffic condition may be transmitted from the track relay and to the battery end of the track circuit, such a control being illustrated for instance in the track circuit 6-9 for the main track of the passing siding B; and (2) a special control code for transmitting an additional control from the track battery end to the track relay end as, for instance, illustrated for the track circuit extending from the signal S3 to the signal S4. In fact, this track circuit extending from the signal S3 to the signal S4 is provided with both of these features, and in order to get a better understanding of these additional features of control this track circuit will be presently more specifically described.

Referring to the track circuit extending from signal S3 to signal S4 this track circuit is provided with a main track battery B3-4 at the east end thereof and a main track relay 3-4T at the west end thereof. This track battery B3-4 and track relay 3-4T are only intermittently con-

nected in series for reasons already explained in connection with the system shown in Figs. 1A-1E. This track relay 3-4T may be intermittently picked up at two different code rates of impulses, namely, either at a frequency of 75 impulses per minute or at 120 impulses per minute as determined by the coding relay 3-4CPR. This coding relay 3-4CPR may be intermittently picked up at either the 75 impulse per minute code rate or the 120 impulse per minute code rate as determined by the contact 54⁶ of the inverse track repeater relay 6ITPP. This contact 54⁶ when up connects the coding relay 3-4CPR to a source of current through the front contact 65⁶ of the coder 120CT6 and when down connects it to a source of current through the front contact 66⁶ of the coder 75CT6, and the coding relay 3-4CPR may, therefore, be energized at coding rates of 120 and 75 impulses per minute, respectively. For energy saving purposes the coder 120CT6 is energized through the front contact 67⁶ of the inverse track repeater relay 6ITPP and, therefore, functions only when an inverse code is transmitted from east to west through the track circuit extending from signal S3 to signal S6. If the track relay 3-4T is intermittently picked up at the rate of 75 times per minute, and this functioning is repeated in the track repeater relay 3-4TP by intermittent picking up thereof, the relay 3-4HTP will be controlled in a manner as more clearly described in the prior application to Phinney, Ser. No. 362,636 filed October 24, 1940; whereas, if this track relay 3-4T is picked up at the 120 impulse per minute code frequency the distant relay 3-4DTP as well as the relay 3-4HTP is continuously energized for reasons pointed out in said Phinney application. This functioning is based on the assumption that the front contact 55⁴ controlled by the home magnet HG of the mechanism M4 of the signal S4 is then in its energized position.

It will be seen that the inductive kick track repeater relay 3-4TPI is included in an energizing circuit including a secondary winding of the transformer 3-4Tr and a front contact 56² of the inverse track repeater relay 2ITPP. This inductive kick track repeater relay 3-4TPI is picked up in response to the dropping of the track repeater relay 3-4TP by reason of the fact that the relay 3-4TPI is a two-position polar relay so poled that it picks up only due to dying flux due to current supplied to transformer 3-4Tr through front contact 68³⁻⁴ of track repeater relay 3-4TP. This construction is employed to obtain quick response, namely, energization of a relay in response to the opening of a front contact rather than due to the closing of a back contact of the track repeater 3-4TP. In other words, when the flux which resulted from current flowing through front contact 68³⁻⁴ of relay 3-4TP collapses in the transformer 3-4Tr an inductive kick is produced in the secondary windings of this transformer which is of a polarity to result in the picking up of the inductive kick track repeater relay 3-4TPI providing the contact 56² is then closed. Referring again to this inductive kick track repeater relay 3-4TPI (see Fig. 4B) this relay is picked up each time that the track repeater relay 3-4TP begins to drop, and by such picking up lifts its contact 23³⁻⁴ to connect the inverse code battery IB3-4 to the track rails between the impulses of the main track circuit including track battery B3-4 and track relay 3-4T. During this time (contact 23³⁻⁴ up) the contact 25³⁻⁴ of the coder relay

21

3-4CPR (see Fig. 4C) is in its retracted position and connects the inverse track relay 3-4IT to the track circuit. In other words, if the contact 56² of the relay 2ITPP (see Fig. 4B) is closed and the contact 23³⁻⁴ of the relay 3-4TPI is intermittently picked up in synchronism with the intermittent dropping of contact 25³⁻⁴ of the coder relay 3-4CPR the inverse track relay 3-4IT (see Fig. 4C) is also intermittently picked up (track assumed unoccupied) as a result of which the inverse track repeater relay 3-4ITP is continuously picked up and reflects that the contact 56² of relay 2ITPP is closed.

Reviewing now the functions performed by the track circuit extending from signal S4 to signal S3, the basic portion of the track circuit comprises the track battery B3-4 and the track relay 3-4T in series. These elements perform two functions of detecting the presence of a train and by the provision of the intermittent closure thereof by front contact 25³⁻⁴ causes contacts 18³⁻⁴ and 20³⁻⁴ to be operated in substantial synchronism. The third function performed by this composite track circuit resides in the manifestation of the presence of a train therein at the track source thereof, namely, by the intermittent picking up of the approach relay 3-4AT resulting in the continuous picking up of the approach repeater relay 3-4ATP. The fourth function performed by this composite track circuit resides in the manifestation at the east end of the section (track battery end of the track circuit) the closed or open condition of the contact 56² of the relay 2ITPP located at the west end. The fifth function performed by this composite track circuit resides in the manifestation at the relay end of the track circuit the conditions of traffic in section next in advance (section from signal S3 to S6). With this section next in advance unoccupied the coding contact 25³⁻⁴ is coded at the 120 impulses per minute rate instead of at 75 impulses per minute. This causes the distant repeater relay 3-4DTP to be energized with the energized home track repeater relay 3-4HTP. The decoding apparatus associated with track repeater relay 3-4TP will now be briefly described.

The decoding transformer 3-4Tr is provided with a center tapped secondary winding, the mid-tap of which is connected through the home repeater track relay 3-4HTP to the rectifying contact 69³⁻⁴ of the track repeater relay 3-4TP. It will be seen that intermittent picking up of the track repeater relay 3-4TP will result in energization of the primary winding of the decoding transformer 3-4Tr in alternate opposite directions. This will induce in the secondary windings of this transformer an alternating current of rather square shaped wave form. This alternating current is in turn rectified by contact 69³⁻⁴ and applied to the home track repeater or decoding relay 3-4HTP and picks it up irrespective of whether the track circuit is then coded at the 75 impulse per minute rate by the contact 66⁶ of the coding relay 75CT6 or is coded at the 120 impulse per minute rate by the contact 65⁶ of the coding relay 120CT6. The distant track repeater or decoding relay 3-4DTP on the other hand is only picked up when a code of 120 impulses per minute is received, the primary circuit for the transformer 3-4DT being tuned to a frequency of 120 cycles per minute by the condenser 3-4C. This tuning of the input circuit for transformer 3-4DT allows sufficient current, when of 120 cycle per minute frequency is applied to this transformer so that when this

22

current is rectified by the rectifier 3-4R it will pick up the distant decoding relay 3-4DTP; whereas, insufficient current will flow to this transformer 3-4DT if the track repeater relay 3-4TP is picked up and dropped away 75 times per minute in response to the coding of the track circuit by the contact 66⁶ of the coding relay 75CT6. The inductive kick relay 3-4TPI is really not a part of the decoding apparatus, the function of this relay being to pick up in response to the collapse of flux of a certain magnetic polarity in the core of the transformer 3-4Tr, this being a polarized relay to allow it to operate only in response to current from transformer 3-4Tr of one particular polarity, namely, the polarity of current that flows when front contact 68³⁻⁴ of relay 3-4TP suddenly opens.

There is another difference in the structure illustrated in Figs. 4A-4E from that shown in Figs. 1A-1E and that is the manner in which the approach lighting circuits for the various signals are controlled. It will be seen from Figs. 1A-1E that the approach lighting circuits are controlled by signal repeater relays, whereas in the Fig. 4A-4E construction they are controlled by back contacts 46 of the home magnets HG of the associated signal mechanism for the intermediate signals S3 and S4, but are controlled by the back contacts 46 of the home magnets of both the associated signal and the opposing signal at the end of each passing siding. The intermediate signals are provided with additional approach lighting contacts which have been designated 58 and which each comprise a front contact of a normally deenergized approach track repeater relay of the track circuit for the track section in approach to the signal. In other words, the signal lamp L4 for the signal S4 is energized if the approach track repeater relay 2ATP is in its attracted position to close its front contact 58² and is also energized if the home magnet HG of the mechanism M4 of the signal S4 is in its retracted position to close its back contact 46⁴. The same is true of the signal lamp L3 associated with the signal S3, and for this reason the control contacts for these approach light circuits have been designated by like reference characters having distinctive exponents. For controlling the inductive track repeating relays 2TPI, 6TPI and 8TPI there are provided respectively the contacts 59¹, 59⁶ and 59⁹ of the directional stick relays 1S, 6S and 9S included in series with switch repeating contacts 53SWE, 53SWW, and 53SWEB respectively, and included in multiple with the front contacts 56¹, 56⁶⁻⁹ and 56⁹⁻⁶ of the track repeater 1ITPP, 6-9HTP and 9-6ITPP, respectively, as heretofore discussed in connection with the inductive track repeater relay 3-4TPI. It is thus seen that an inverse code is not sent toward the first opposing signal in the single track section if either the main track is occupied by a train moving toward such signal or the track switch between such main track and opposing signal is in the take-siding position but is sent of a train on the main track is moving in the opposite direction (directional stick relay associated with entering signal, such as S1, energized). This feature performs a so-called caution tumble-down function for a train ready to enter the single track section.

Operation Fig. 4.—The operation of the apparatus illustrated in Figs. 4A-4E during movement of a train from left to right over the signaling system will now be described by making reference

to the signal aspects, the fact whether they are lighted and the train positions illustrated in Figs. 5A-5I inclusive. Referring first to Fig. 5A it will be seen that without any trains around all of the signal aspects are dark signals with their mechanisms in the clear "G" position, except the head-block signals for the side track which are in their stop or "R" position.

Referring now to Fig. 5B it will be seen that there is a train occupying the main track of the passing siding A and that the presence of this train places the signal S1 in its stop position and illuminates each one of the signals S1, S2 and S2A and that the presence of this train also puts the signals S3 and S5 in the caution position. In other words, a caution tumble-down as distinguished from a stop tumble-down of signals takes place. Let us now refer to Figs. 4A-4E of the drawings and see how this operation takes place.

The presence of the train on the main track of the passing siding A (see Fig. 5B) deenergizes the inverse track relay 2IT continuously (see Fig. 4A) thereby deenergizing the inverse track repeater relay 2ITPP, which by the opening of its contact 19¹ deenergizes both the home magnet HG and the distant magnet DG of the signal mechanism M1 of the signal S1. The dropping of the magnet HG of the mechanism M1 by the closure of its back contact 46¹ closes circuits to illuminate the signal lamps L1, L2 and L2A. The distant magnet DG of the mechanism M1 is, of course, also operated to its retracted position in which position the pole-changer contact 17¹ and 22¹ are operated thereby causing the approach home relay 3AHD to assume its left-hand position and by the operation of its polar contacts toward the left applies current of reverse polarity to the two windings of the mechanism M3 of the signal S3. This pole changing of the line circuit results in deenergization of the magnet DG of the mechanism M3, but leaves the home magnet HG of this mechanism M3 still energized and in its attracted position. This will cause the signal S3 to assume its caution position with its lamp L3 extinguished (see Fig. 5B) because the back contact 46³ of the home magnet HG of mechanism M3 is still open. Since the home magnet HG of the mechanism M3 is still in its attracted position its front contact 61³ is still closed. The inverse track repeater relay 3-4ITP is, however, deenergized in spite of the closed contact 61³ because the front contact 62²⁻⁴ of the relay 3-4ITP is open. This contact 62²⁻⁴ is because there is no inverse code received at the east end of the track circuit extending from S4 to signal S3 by reason of the fact that the inductive kick repeater relay 3-4TPI (see Fig. 4B) which creates the inverse code is continuously deenergized, it being continuously deenergized because no inverse code is received at the east end of the track circuit extending from signal S1 to signal S4 to hold up the contact 56² of the relay 2ITPP included in the energizing circuit of the inductive kick repeater relay 3-4TPI. That is, the inverse track relay 2IT is continuously deenergized and its repeater track relay 2ITPP is deenergized to open its contact 56², because no inverse code is received at the east end of this track circuit between signals S1 and S4. No inverse code is received because the inductive kick repeater relay 2TPI (see Fig. 4A) is continuously deenergized by reason of the fact that the front contact 56¹ of the inverse code repeater relay 1ITPP is continuously deenergized by the presence of the train on the main track of the passing

siding A. The contact 59¹ of the directional stick relay 1S connected in multiple with this contact 56¹ is, of course, also open this relay 1S being picked up for west-bound train movements only. In other words, the presence of the train on the main track of passing siding A causes the signal S3 to assume its caution position because the mechanism M1 of the signal S1 is in its stop position and by dropping the pole-changer contacts 17¹ and 22¹ causes reversal of the current in approach home-distant relay 3AHD, which in turn pole changes the energizing circuit for the signal mechanism M3, which in turn causes its spectacle to be operated to the caution position and emit a yellow beam of light upon approach lighting of its lamp L3. The presence of this train on the main track of the passing siding A on the other hand causes the signal S5 to assume the caution position by pole changing the energy applied to the mechanism M5 due to dropping of the inverse track repeater relay 3-4ITPP (Fig. 4C) because the presence of the train on the main track of passing siding A opens the contact 56² of the inductive kick repeater relay 2TPI which prevents its coding and which in turn causes continuous deenergization of the inverse code repeater relay 2ITPP, which in turn by opening of its contact 56² permanently deenergizes the inductive kick repeater relay 3-4TPI and which in turn causes continuous deenergization of the inverse code repeater relay 3-4ITPP (see Fig. 4C). This latter inverse track repeater relay 3-4ITPP causes the operation of its pole-changer contacts 17³⁻⁴ and 22³⁻⁴ which in turn causes current of reverse polarity to flow through the mechanism M5 of the signal S5 thereby placing this signal S5 in its caution position.

It will be seen from the foregoing that the presence of a train on the main track of one passing siding is manifested by the opposing starting signal at the passing siding next in advance being in its caution position in the Fig. 4A-4E structure as distinguished from the Fig. 1A-1E structure (see Fig. 3A) where no such manifestation of a train at the siding next in advance is given. Even though the signals S3 and S5 have been operated from the clear to the caution position they are still dark signals (see Fig. 5B) because their respective signal lamps L3 and L5 are still extinguished. Should, however, there be a train on the main track of the passing siding B its presence would put the signal S6 to stop and thereby close the approach lighting contact 46⁶ in the energizing circuit of the lamp L5 resulting in the illumination of this lamp L5 as well as lamps L5A and L6, so that the engineer of this west-bound train at passing siding B would be aware of the presence of the east-bound train at passing siding A, because of the caution aspect given by the illuminated lamp in the signal S5.

Let us now assume that the train under consideration advances upon the detector track section associated with the east end of the passing siding A as illustrated in Fig. 5C. This acceptance of the train under consideration of the signal S2 by passing it causes deenergization of the detector track relay DTE, thereby closing a pick-up circuit for the directional stick relay 2S by the closure of the back contact 40^{DTE2} of the detector track relay DTE. The picking up of this directional stick relay 2S causes its stick circuit including its stick contact 32² to be closed. The directional stick relay 1S is, however, not picked up because its pick-up circuit is open at front contact 31¹ of the magnet HG of the signal mech-

anism M1. As the train later advances a little further and passes the signal S1 a supplemental stick circuit including the back contact 40² of the home track repeater relay 2HTP will be completed.

Let us, however, continue in our assumption that the east-bound train under consideration has only passed the signal S2 and has not yet passed the signal S1. The presence of the train on the detector track circuit including the track relay DTE also opens at its front contact 42DE the circuit for the approach home relay 3AHD (see Fig. 4B) the dropping of which at its front contacts 37³ and 38³ opens the energizing circuit for both the home and distant magnet of the signal mechanism M3 for the signal S3 (see Fig. 4C). This causes the signal S3 to assume the stop position and by the closure of its back contact 46³ causes the lamp L3 for this signal S3 to be illuminated.

Also, dropping of the home magnet HG of the signal mechanism M3 of the signal S3 causes the opening of its front contact 63³, thereby opening the energizing line circuit for the mechanism M5 of the signal S5, the front contact 24³ of the directional stick relay 3S being open, so that this signal S5 also assumes the stop position. Operation of the signal mechanism M5 to its stop position (both magnets DG and HD in their retracted position), causes the pole-changer contacts 17⁵ and 22⁵ to be operated to their position in which position current of reverse polarity is applied to the signal mechanism M9 through a line circuit including the back contact 22⁵ of mechanism M5, front contact 44^{DW} of detector track relay DTW, front contact 45⁸ of the home track repeater relay 6HTP, back contact 21⁶ of the directional stick relay 6S, oscillating contact 18⁶⁻⁹ of the track relay 6-9T, front contact 19⁶⁻⁹ of the home track repeater relay 6-9HTP, front contact 19⁹⁻⁶ of the inverse track repeater relay 9-6ITPP, vibratory contact 20⁹⁻⁶ of the coder 75CT9-6, front contact 43^{DEB} of the detector track relay DTEB, switch repeating contact 50^{SWEB} and back contact 21⁸ of the directional stick relay 8S, through the mechanism M9 and back through a line wire through the pole-changer contact 17⁵ to the source of current. The current of negative polarity in this circuit causes the distant magnet DG of the mechanism M9 to be operated to its deenergized position thereby placing the signal S9 in its caution position, but with its signal lamp L9 still extinguished.

Dropping of the distant magnet DG of the mechanism M9 of signal S9 will, of course, operate the pole-changer contacts 17⁹ and 22⁹ to cause the signal S11B, next in the rear of the signal S9, to also be operated to its caution position by a circuit not completely shown, but shown for the signal S3. It is, of course, understood that under the traffic conditions illustrated in Fig. 5C that even though the signals S9 and S11B are dark signals with their mechanisms in the caution position these signals will be illuminated as soon as there is an approaching train by reason of approach lighting contacts heretofore described.

Let us now assume that the train under consideration enters the track circuit between signals S1 and S4 as illustrated in Fig. 5D of the drawings. This produces no change in the signal aspects except that the approach lighting circuit for the lamp L4 of the signal S4 is now closed at front contact 58² of the approach code repeater relay 2ATP. This approach code re-

peater relay 2ATP is now energized because the presence of the train in the track circuit in which the approach track relay 2AT is included causes the relay 2AT to be intermittently picked up, 5 because the presence of the train on this track circuit allows enough current to flow for this series approach relay 2AT to pick it up. This in turn results in its code repeater relay 2ATP being continuously picked up to close the approach lighting contact 58². Another function that takes place with the train occupying this track section is that the supplemental stick circuit for the directional stick relay 2S is now closed at the back contact 40² of the home code repeater relay 15 2HTP. This home code repeater relay 2HTP is obviously continuously deenergized because the track relay 2T and the repeater relay 2TP which control it are continuously deenergized. Another function performed by the east-bound 20 train's movement past the signal S1 resides in the holding of this signal S1 at stop by the open back contact 21² of the directional stick relay 2S rather than by the formerly open front contact 43DE of the detector track relay DTE.

Referring now to Fig. 5E, let us now assume that the train under consideration has accepted the signal S4 by passing it, this causes continuous deenergization of the track relay 3-4T and causes continuous energization of the approach 30 track relay 3-4AT (Fig. 4C). This, of course, causes continuous deenergization of the home track repeater relay 3-4HTP resulting in the opening of its contact 19³⁻⁴ included in the circuit of both the home magnet HG and the distant magnet DG of the mechanism M4 of the signal S4. However, before the home magnet HG of the mechanism M4 assumes its retracted position the back contact 40³⁻⁴ of the home track repeater relay 3-4HTP is closed, resulting in 35 the closure of a pick-up circuit for the directional stick relay 4S, the front contact 40^{2A} of the approach repeater track relay 2ATP now being closed. As soon as this stick relay 4S is picked up it is stuck up through its stick circuit including its stick contact 32⁴ and back contact 40³⁻⁴ of relay 3-4HTP. After a short period of delay the home magnet HG of mechanism M4 drops and establishes a supplemental stick circuit for directional stick relay 4S at back contact 31⁴. With the directional stick relay 4S now energized and the home magnet HG of the mechanism M4 deenergized and with the distant track repeater relay 3-4DTP deenergized a caution circuit, energized by current of reverse polarity, for the mechanism M2 of the signal S2 is closed as soon as the rear end of the train vacates the track circuit extending from signal S1 to signal S4. This caution circuit, among other things, may include the pole-changer contacts 17³⁻⁴ and 22³⁻⁴ in their retracted position, back contact 63⁴ of the home magnet HG of the mechanism M4 and front contact 24⁴ of the directional stick relay 4S. The energization of this caution 50 circuit for the mechanism M2 of signal S2 by current of reverse polarity, of course, will cause the home magnet HG only to pick up, and cause the distant magnet DG to remain in its retracted position thereby operating the spectacle for the signal S2 to its caution position. Since, however, the back contact 46² of this home magnet HG is open this caution signal S2 will be a dark signal as will also the signals S1 and S2A associated with the same track switch, (see Fig. 5E). Another function that takes place as the rear 55 end of the train passes the signal S4 resides in

the clearing of the opposing signal S4. This is accomplished by the dropping of the directional stick relay 2S and the closure of its back contact 21² included in series with the circuit for the mechanism M1. This directional stick relay 2S is dropped in response to the picking up of the home code repeater relay 2HTP and the opening of its back contact 40². This home code repeater relay 2HTP is, of course, picked up because the track relay 2T is intermittently picked up at the 75 impulse per minute code rate as soon as the train under consideration vacates the track circuit in which this track relay 2T is included.

Referring now to Fig. 5F the movement of the east-bound train by the opposing signal S3 produces no particular result except that it operates the mechanism of the signal S9 from the caution to the stop position which incidentally also results in the illumination of the signal lamps in each of the signals S9, S8 and S8A. Referring to Fig. 4C the movement of the east-bound train by the opposing signal S3 causes continuous deenergization of the track relay 6T and the approach track relay 6AT. The picking up of approach repeater relay 6ATP causes closing of its front contacts 40⁶ and 58⁶. Closure of contact 58⁶ merely closes another circuit for the already lighted lamp L3 and closure of contact 40⁶ does not affect the stick relay 3S because its pick-up circuit is open at front contact 31³ of mechanism M3. The dropping of track relay 6T causes continuous deenergization of the home code repeater relay 6HTP, opening its contact 45⁶ (the multiple branch is open at contact 24⁵) and opening the formerly closed caution circuit energized by current of reverse polarity for the mechanism M9 of the signal S9 at this front contact 45⁶, so that the mechanism M9 is completely deenergized causing the spectacle thereof to assume the stop or "R" position. Under this condition the home magnet HG of its mechanism M9 is, of course, in its retracted position and at its back contact 46⁹ closes energizing circuits for the signal lamps L9, L8 and L8A. The apparatus under consideration is now in the condition illustrated in Fig. 5F of the drawings.

If the train under consideration now accepts the signal S6, by passing it, this signal S6 is changed from the clear or "G" condition to the stop or "R" condition. This is accomplished through the deenergization of the detector track relay DTW which by the opening of its front contact 42^{DW} breaks the energizing circuit for the mechanism M6 for the signal S6. In all other respects the apparatus has been unchanged by the movement of the front end of this train by the signal S6, with the exception that the directional stick relay 6S was picked up through a circuit extending through switch repeating contact 52^{sww}, the back contact 40^{DW6} of the detector track DTW and front contact 31⁶ of mechanism M6. The opening of front contacts 42^{DW} and 44^{DW} merely result in the opening of additional contacts in already open circuits.

Referring now to Fig. 5H of the drawings, the movement of the front end of the train by the opposing signal S5 produces no result in the signaling apparatus in any respect, this by reason of the fact that the detector track relay DTW is still deenergized and it maintains open at its front contact 42^{DW} in the energizing circuit for the approach home relay 4AHD, which in turn by its open front contacts 37⁴ and 38⁴ holds open the energizing circuit for the magnets of mechanism

M4 of the signal S4. Also, the presence of this train on the detector track circuit still holds the signal S3 at stop because, as just pointed out, the mechanism M4 of the signal S4 is still wholly deenergized and holds the directional stick relay 4S up through a stick circuit including the back contact 31⁴ of the home magnet HG of the mechanism M4, so that with this directional stick relay 4S in its attracted position it holds its back contact 21⁴, which is included in series in the energizing circuit of the approach relay 3AHD, open thereby continuing the deenergization of this approach relay 3AHD and the opening of its front contacts 37³ and 38³, which are included in series in the energizing circuit for the magnets of mechanism M3 of the signal S3, to hold it deenergized, so that this signal S3 remains in its stop position with its signal lamp energized.

Let us now assume that the train under consideration moves into the main track of the passing siding B to an extent as shown in Fig. 5I, namely, so that its rear end clears the detector track circuit associated with the track switch SwW. This vacating of the detector track circuit containing the detector track relay DTW (See Fig. 4D) causes its front contact 42^{DW} included in the energizing circuit for the approach home relay 4AHD to be closed. Since, however, the magnet M6 for the signal S6 is in its deenergized condition by reason of the open contacts 10⁶⁻⁹ and 19⁹⁻⁶ of the relays 6-9HTP and 9-6ITPP, respectively, these contacts continue to hold the pole-changer contacts 17⁶ and 22⁶ in their retracted position, so that the current supplied to the approach home relay 4AHD is of reverse polarity as soon as the contact 42^{DW} of detector relay DTW closes, thereby causing polar contacts of relay 4AHD to be operated to the left-hand position. With these polar contacts 36⁴ and 39⁴ of the relay 4AHD in their left-hand position current of reverse polarity is applied to the mechanism M4 of the signal S4, thereby causing the home magnet HG thereof to be energized but the distant magnet DG thereof to remain in its retracted position. This causes the mechanism M4 of the signal S4 to assume the caution "Y" position, but is a dark signal because its lamp L4 has been deenergized by the opening of the back contact 46⁴ of the mechanism M4. The operation of the signal mechanism of signal S4 from its stop position to its caution position results in deenergization of the directional stick relay 4S at back contact 31⁴ of the mechanism M4. This causes reclosure of back contact 21⁴ of stick relay 4S and the re-energization of the approach home relay 3AHD. The closure of its front contacts 37³ and 38³ results in the re-energization of the signal mechanism M3 and the clearing of signal S3, assuming that there is no train following the train under consideration. This signal S3 will, however, remain dark until a train approaches it by reason of its approach lighting as provided by front contact 58⁶ of approach repeater relay 6ATP.

Since the track circuit extending from signal S3 to signal S6 has its main track relay 6T at the east end the vacancy of this track circuit cannot be manifested at the west end of this track circuit and it will be necessary to manifest this unoccupancy of this track circuit at the west end by the intermittent picking up of the inverse code track relay 6IT at the west end of this track circuit. This inverse track circuit including inverse track relay 6IT and inverse track battery 1B6 is brought back into play by closure of the energizing circuit for the inductor kick repeating relay 6ITPI at front contact 59⁶ of the

directional stick relay **6S**. This directional stick relay **6S** was, of course, picked up by the east-bound train under consideration passing the signal **S6**. The inverse track circuit including inverse track relay **6IT** and inverse track battery **IB6** is now intermittently energized by the intermittent picking up of the inductive kick repeating relay **6ITPP** due to reception of the main code by the track relay **6T**. The inverse track relay **6IT** is, therefore, intermittently picked up and its repeater inverse track relay **6ITPP** is continuously held up to manifest that there is no train in the track section from signal **S3** to signal **S6** and that the directional stick relay is in its attracted position with the main track of the passing siding **B** occupied by a train. With the inverse track repeater relay **6ITPP** now in its attracted position it applies coded current of 120 impulses per minute to the track circuit including track battery **B3-4** through the medium of code repeating relay **3-4CPR**. This causes the distant code responsive relay **3-4DTP** (see Fig. 4B) to pick up and pole change the line circuit for the signal mechanism **M2** to cause it to be energized by current of normal polarity. This results in the operation of this mechanism **M2** to its clear position to clear the signal **S2**. It should be understood, however, that the signal **S4** will remain in its caution position because it is not controlled by the distant **3-4CPR** but its mechanism **M4** is energized by current of reverse polarity, because the approach home-distant relay **4AH** is now energized by current of reverse polarity through back contacts **17⁶** and **22⁶** of the distant magnet **DG** of mechanism **M6**. The signals of the system now have their mechanisms assuming positions as illustrated by the letters **G**, **Y** and **R** in Fig. 5I of the drawings signifying clear, caution and danger respectively, and with their signal lamps illuminated as illustrated in this Fig. 5I. Since the train under consideration now occupies the same position in the passing siding **B** that it occupied in the passing siding **A** as illustrated in Fig. 5B a complete movement of an east-bound train from one passing siding to the other passing siding has been specifically described.

Let us now assume that there is a train standing on the side track of passing siding **A**. Since this track portion is not provided with a track circuit the signals will be all dark signals as illustrated in Fig. 5A with their mechanism assuming aspect positions as illustrated by the letters **G** and **R** in Fig. 5A. Let us now assume that this train on the side track of passing siding **A** is travelling in an eastwardly direction and has a train order to enter a single track section, providing that the signal **S2A** assumes a proceed position. The brakeman of the train will in response to this train order operate the track switch **SwE** to the take-siding position. This will result in the opening of contacts **48^{SwE}**, **50^{SwE}** and **52^{SwE}**. The opening of the contact **50^{SwE}** will result in the deenergization of the mechanism **M1** thereby causing the signal **S1** to assume its stop position in which position of the mechanism its signal lamp **L1** as well as the signal lamps **L2** and **L2A** will be illuminated through back contact **46¹** of mechanism **M1**. The closure of the contact **49^{SwE}** and the opening of the contact **48^{SwE}** will cause the mechanism **M2A** to be substituted for the mechanism **M2**. If there is no train anywhere in the single track section or on the main track of the next passing siding in advance, this signal **S2A** will assume its clear posi-

tion. If, however, there is a west-bound train on the main track of the passing siding **B** the signal **S2A** will assume the caution position, and if such train on the main track or passing siding **B** has advanced past the signal **S5** this signal **S2A** will assume the stop position, all for reasons already pointed out for east-bound traffic. The engineer on the side track of passing siding **A** will thus be clearly informed as to traffic conditions in advance before he will attempt to pass the signal **S2A**. The movement of the mechanism of signal **S1** to its stop position as just explained, will, of course, for reasons heretofore given cause the signal **S3** next in the rear thereof to assume the caution position. As this train which advances off of the side track of passing siding **A** passes through the single track section the signaling apparatus will function in a manner substantially the same as described when an east-bound train passed off of the main track of the passing siding **A** as heretofore described. There are, however, two differences between the functioning of the apparatus as the train moves off of the main track or the side track of the passing siding **A** in an eastwardly direction.

(1) When the train moves off of the main track at passing siding **A** the directional stick relay **2S** is picked up by the back contact **40^{D2}** of the detector track relay **DTE**, and the front contact **31²** of the mechanism **M2**, but this is not possible when the train moves off of the side track because the operation of the switch **SwE** has resulted in the deenergization of the magnet **M2** so that the pick-up circuit under consideration would be open at the front contact **31²** of the home magnet **HG** of the mechanism **M2**. This stick relay **2S** is, however, picked up through a similar pick-up circuit including the front contact **31^{2A}** of the mechanism **M2A** when the train on the side track passes upon the detector track circuit including track relay **DTE**. As the train on the side track of the passing siding **A** now moves into the single track section this directional stick relay is continued to be stuck up through an auxiliary stick circuit including the back contact **40²** of the home track repeater relay **2HTP**, back contacts **31²** and **31^{2A}** of the home magnets **HG** of the mechanisms **M2** and **M2A**, respectively, and the stick circuit **32²** of the directional stick relay **2S**. The second difference (2) resides in the fact that the caution tumble down is accomplished by the opening of the inductive kick repeater relay circuit at switch repeating contact **53^{SwE}** when the track switch **SwE** is opened instead of opening it at front contact **56¹** of relay **6ITPP** when the main track of passing siding **A** became occupied. It is thus seen that even though the directional stick relay **2S** is picked up differently this stick relay will remain up if a train passed off of the side track of the passing siding **A** and into the single track section upon the return of the switch to its normal main-track position.

We have now explained all phases of operation of the signals and associated apparatus in response to an east-bound train moving through the single track section and through the passing siding **B**. It would at first hand appear to be unnecessary to show the effect that a west-bound train would have by its movement through the passing siding **B** and the single track section illustrated. Although the signal aspects of opposing signals ahead of a train and the signals governing in the same direction to the rear of the train is exactly

75 the same whether the train is an east-bound train

or a west-bound train the apparatus for obtaining these controls over the signals are somewhat different, and for this reason it is desired to consider the movement of a west-bound train through the section of a track illustrated in Figs. 4A to 4E, inclusive. In considering this operation of the system due to a west-bound train moving thereover attention is directed to Figs. 6A to 6J, inclusive, which illustrate the signal aspects as well as the fact whether the signals are lighted or dark for various locations of a west-bound train on the system illustrated in Figs. 4A to 4E, inclusive.

Referring to Fig. 6A it will be seen that all of the signals except the signal governing traffic off of the side track of the passing sidings are at proceed with their signal lamps extinguished and that the signals which govern off of the side track of the passing siding having their mechanisms in the stop or "R" condition with their signal lamps also extinguished. In fact, the signal aspects of Fig. 6A are identical to those of Fig. 5A.

Let us now assume that a train has accepted the signal S11B, by passing the same, and that it assumes a position on the track as illustrated in Fig. 6B of the drawings. Under this condition of traffic the signals S10B and S8 will have their mechanisms assume the stop position as indicated by the letters "R" and with the signal S8 in the stop position the next two signals in the rear thereof, namely, signals S6 and S4 will both assume the caution position. It will also be seen that the lamps for the signals S11B, S10B, S8, S8A and S9 all have their signal lamps lighted. Referring now to Fig. 4E of the drawings although the apparatus associated with signals S10B and S11B has not been illustrated in Fig. 4E it readily becomes apparent from Figs. 4B and 4C of the drawings that the presence of the west-bound train between the signals S10B and S11B will cause the signal S10B to assume its stop position, under which condition its signal lamp is lighted and that the mechanism M10B (not shown but controlled identically the same as mechanism M4) will be in its deenergized condition and thereby deenergizing the distant relay (not shown) which corresponds to the distant code repeater relay 3-4DTP shown in Fig. 4B of the drawings. Since the directional stick relay associated with the signal S10B (not illustrated but corresponding to relay 4S) is in its deenergized condition (this directional stick relay being picked up by an east-bound train only) it immediately becomes apparent that the circuit for energizing the mechanism M8 (see Fig. 4E) is open at the front contact of the home magnet of the signal mechanism M10B (not shown but corresponding to front contact 63⁴ of mechanism M4) and is also open at the front contact of the directional stick relay 10BS (not shown but corresponding to the front contact 24⁴ of the signal 4S) so that the mechanism M8 for the signal S8 is completely deenergized and holds the signal S8 in its stop position, as illustrated in Fig. 6B.

With the signal mechanism M8 deenergized and with the directional stick relay 8S deenergized (see Fig. 4E) it is readily seen that one energizing circuit for the mechanism M6 (see Fig. 4D) is open at the front contact 24⁸ of the directional stick relay 8S (see Fig. 4E). There is, however, another energizing circuit for the mechanism M6 which includes the front contact 45⁸ of the home code repeater relay 8HTP and the front contact 44^{DEB} of the detector track relay DTE in series, which is closed under the conditions under

consideration so that the mechanism M6 is energized by current of negative polarity through the back contacts 17⁸ and 22⁸ of the home magnet HG of the mechanism M3. This causes the mechanism M6 to assume its caution position resulting in operation of its spectacle to the caution or yellow position as illustrated in Fig. 6B. The signal S6, however, remains a dark signal since the energizing circuit for its signal lamp L6 is open at the back contact 46⁶ of the magnet HG of the mechanism M6. Since the energizing circuit for the approach home-distant relay 4AHD (see Fig. 4C) may be pole changed by the distant magnet DG of the mechanism M6, instead of by the home magnet HG as is generally the case, the approach home distant relay 4AHD is energized by current of reverse polarity through a circuit including back contacts 17⁶ and 22⁶ of the distant magnet DG of the mechanism M6. With the approach home distant relay 4AHD now assuming its left-hand energizing position current of reverse polarity is applied by its polar contacts 36⁴ and 39⁴ assuming the left-hand position to the line circuit for energizing the mechanism M4 of the signal S4. Current of reverse polarity flowing through the mechanism M4 of the signal S4 will cause its spectacles to assume the caution position in which it will emit a yellow beam of light as soon as its signal lamp L4 is lighted. The signal S4 for the present, however, remains a dark signal, and the signal mechanisms assume the indicating positions and have their signal lamps lighted or extinguished all as shown in Fig. 6B of the drawings under the traffic condition assumed.

Let us now assume that the train under consideration has moved from the track section between signals S10B and S11B and into the track section between the signals S9 and S10B, as shown in Fig. 6C of the drawings. The movement of the west-bound train into the track section extending from signal S9 to signal S10B causes de-energization of the home code repeater relay 8HTP (see Fig. 4E). The dropping of this relay 8HTP by the opening of its front contact 45⁸ opens the caution or inverse polarity circuit for the mechanism M6 to which the reference has just been made, the directional stick relay 8S being down. The breaking of this caution circuit for the mechanism M6 causes the home magnet HG of the mechanism M6 to also assume its retracted position, thereby causing the signal S6 to give a danger aspect by the movement of the red spectacle in the path of the beam emitted by its lamp L6, this lamp L6 now being energized through a circuit including the back contact 46⁶ of the home magnet HG of the mechanism M6. Not only does this back contact 46⁶ energize the signal lamp L6 but it also energizes the lamps L5 and L5A. In all other respects the signals have not been affected by the movement of the train from the track section extending from signal S10B to the signal S11B into the track section extending from the signal S9 to the signal S10B.

Let us now assume that the west-bound train accepts the signal S9 by moving by it and upon the detector track section containing the detector track relay DTEB. The movement of the west-bound train by the signal S9 results only in the movement of the signal S9 to the stop position. This operation of the signal S9 to its stop position is accomplished by deenergization of the mechanism M9 by the opening of the front contact 43^{DEB} of the detector track relay DTEB. It

may, however, be pointed out that the directional stick relay 9S was picked up just prior to the de-energization of the mechanism M9 through a pick-up circuit which may be traced from a terminal (+), through the normal switch repeating contact 52^{SWEE}, the back contact 40^{DE9} of the detector track relay DTEB, through front contact 31⁹ of the home magnet HG of the mechanism M9 and through the winding of the directional stick relay 9S to the other terminal (-) of the same source. With this directional stick relay 9S once picked up its stick circuit includes the stick contact 32⁹ and also includes the contacts 52^{SWEE} and 40^{DE9}, just referred to. This picking up and sticking up of the directional stick relay 9S is of no particular consequence at this time but will be discussed hereinafter. The apparatus illustrated in Figs. 4A to 4E is now in the condition as illustrated in Fig. 6D of the drawings.

Let us now assume that the train under consideration moves from a position as illustrated in Fig. 6D to the position illustrated in Fig. 6E of the drawings. As the train enters the main track of the passing siding B it produces no change in the single aspects of the signals in advance of the train except that it moves the signal S2 from its proceed or "G" position, to its caution or "Y" position, and in the rear thereof it allows the signal S11B to assume the caution instead of the stop position and allows the signal S10B to assume the clear instead of the danger position (see Fig. 6E). The signal S11B is permitted to assume its caution position because the energizing circuit for the signal mechanism M11B (not shown) can receive caution current from an approach home distant relay (not shown) similar to the relay 3AHD (see Fig. 4B), which approach home-distant relay receives caution energy through a circuit identical to the circuit for the approach home-distant relay 3AHD (see Fig. 4D) and including the front contact 42^{DEB} of the detector track relay DTEB associated with the west end of the passing siding B and the front contact 19⁸ of the home track repeater relay 8HTP. The directional stick relay 9S is now held energized by a stick circuit including the back contact 40⁹⁻⁶ of the inverse code repeater relay 9-6ITPP and the back contact 31⁹ of the mechanism M9 and this stick relay by its front contact 59⁹ prevents a caution tumble down through the single track section from taking place, the front contact 56⁹⁻⁶ now being open.

It has just been stated that the movement of the west-bound train onto the main track of the passing siding B causes the signal S2 to change from its clear to its caution position, and this phase of the operation of the system conveniently called a caution tumble down will now be described. The presence of the west-bound train on the main track of the passing siding B causes deenergization of the home track repeater relay 6-9HTP (see Fig. 4D). The dropping of this relay 6-9HTP, among other things, opens its front contact 56⁹⁻⁹, to thereby prevent the inductive kick repeater relay 6TPI from picking up in response to the dying of the flux in the transformer 6Tr due to opening of the front contacts 68⁶ and 69⁶ of the track relay 6TP. In other words, the opening of this contact 56⁹⁻⁹ of the relay 6-9HTP stops the sending of an inverse code from the right-hand end or track relay end of the track circuit extending from signal S3 to signal S6, in that it prevents the intermittent picking up of the contact 23⁶ of the inductive kick repeater relay 6TPI so that the inverse coding battery IB6

is not connected to this track circuit during the "off" periods of the main track circuit. This continuous deenergization of the inductive kick relay 6TPI causes continuous deenergization of the inverse track relay 6IT (see Fig. 4C). With this inverse track relay 6IT continuously deenergized the two code repeater relays 6ITP and 6ITPP are both continuously deenergized thereby connecting the coding relay 3-4CPR to the coding contact 66⁶ of a 75 impulse per minute coder 75CT6 instead of allowing its energization at the 120 impulse per minute rate through the front contact 65⁶ of the coder relay 120CT6, as was heretofore the case. This change of the coding rate of the current applied to the coding relay 3-4CPR (see Fig. 4C) causes the track circuit extending from the signal S3 to the signal S4 to be coded at the 75 impulse per minute rate, which in turn causes the deenergization of the distant code repeater relay 3-4DTP (see Fig. 4B) which relay will respond only to a 120 impulse per minute code rate. Dropping of the distant code repeater relay or decoding relay 3-4DTP causes the dropping of its pole-changing contacts 17³⁻⁴ and 22³⁻⁴, which in turn causes pole changing of the energizing circuit for the mechanism M2 associated with the signal S2. The application of current of reverse polarity to the mechanism M2 causes its distant magnet DG to assume its retracted position although its home magnet HG remains in its attracted position, as a result of which the signal S2 assumes the caution or yellow position although it remains a dark signal since its signal lamp L2 remains extinguished due to the fact that the back contact 46² of the mechanism M2 is still open. The train movement as thus far described, assumes the west-bound train to be occupying the main track of the passing siding B which results in signal aspects and signal illustration as illustrated in Fig. 6E of the drawings.

As the west-bound train under consideration now accepts the signal S5 and treads upon the detector track circuit at the west end of the passing siding B the usual tumble-down of signals to danger through the single track section takes place. The entrance of this train upon the detector track circuit containing the track relay DTW shunts this track relay and causes the opening of its front contact 42^{DW} included in the energizing circuit for the approach relay 4AHD (see Fig. 4C). Deenergization of the approach home relay 4AHD by the opening of its front contact 37⁴ and 38⁴ causes deenergization of the mechanism M4 for the signal S4 (see Fig. 4B). Complete deenergization of the mechanism M4, of course, causes the signal S4 to assume its stop position, in which position the back contact 46⁴ of the home magnet HG of this mechanism M4 is closed to result in the energization and illumination of the signal lamp L4. With the mechanism M4 completely deenergized the front contact 55⁴ associated with the home magnet HG of this mechanism M4 is, of course, opened, thereby continuing to hold deenergized the distant code repeater or coder relay 3-4DTP. The caution circuit for the mechanism M2 which was formerly closed through back contacts 17³⁻⁴ and 22³⁻⁴ of the distant code repeater relay 3-4DTP is, however, now broken at the front contact 63⁴ of the mechanism M4, so that the mechanism M2 is now completely deenergized (front contact 24⁴ of relay 4S being open) and causes the signal S2 to assume its stop position. This complete deenergization of the mechanism M2 causes its back con-

tact 46^2 to be closed thereby closing the energizing circuits for the home lamps $L1$, $L2$ and $L2A$ constituting parts of the signals $S1$, $S2$ and $S2A$, respectively, to be closed. Since it was assumed that the rear end of the train still occupied the main track of the passing siding B the signals to the rear of this train have not had their aspects changed in any way and the various signals now assume the indicating positions and condition of illumination as indicated in Fig. 6F of the drawings. It may, however, be pointed out that the two signals successively in the rear of the signal $S2$ will assume their caution position for the same reason that the signals $S4$ and $S6$ assumed their caution position when the signal $S8$ assumes the stop position (see Fig. 6B).

The movement of the train from the position illustrated in Fig. 6F of the drawings to the position illustrated in Fig. 6G of the drawings causes the signal $S3$ which formerly assumed the clear position with its mechanism unlighted to now remain in the same position with its signal lamp $L3$ lighted. This illumination or energization of the signal lamp $L3$ (see Fig. 4C) is accomplished by the picking up of the approach code repeater relay $6ATP$ due to the presence of the train in the track circuit in which the series approach relay $6AT$ is located, to cause the closure of its front contact 58^8 included in the energizing circuit for the signal lamp $L3$. Referring again to Fig. 6G, the movement of the west-bound train off of the main track of the passing siding B and off of the detector track circuit associated with the west end of this passing siding B causes the signal $S9$ to change from its danger illuminated condition to its caution dark condition. This is accomplished by the reclosure of the front contact 196^9 of the home code repeater relay $6-9HTP$ (see Fig. 4D) to allow the flow of current through the front contact 24^5 of the directional stick relay $5S$, as a result of which the mechanism $M9$ for the signal $S9$ is energized by current of reverse polarity resulting in the movement of its spectacle to the caution or "Y" position as illustrated in Fig. 6G. This signal $S9$, however, now is extinguished as are also the signals $S8$ and $S8A$ because their signal lamps have now been extinguished by the opening of the back contact 46^6 of the home magnet HG of the signal mechanism $M9$. It, of course, is understood that the directional stick relay $S5$ was picked up and then stuck up through back 40^6 of relay $6HTP$.

Let us now assume that the west-bound train occupying the section between the signals $S3$ and $S6$ continues its movement and accepts the clear signal $S3$ by passing the same (see Fig. 6H). This advance of the west-bound train under consideration produces no change in the signals ahead of the train except that the signal $S3$ is moved to its stop position. This is accomplished by the presence of the west-bound train on the track circuit between signals $S3$ and $S4$ deenergizing the track circuit and holding the track relay $3-4T$ and the track repeater $3-4TP$ continuously in their deenergized position, as a result of which the home code repeater relay $3-4HTP$ assumes its deenergized position and opens its contact 193^4 included in the energizing circuit of the mechanism $M3$ for the signal $S3$, causing the signal $S3$ to assume its stop position. As the train in question now passed the signal $S3$, as was just assumed, the back contact 40^6 of the relay $6HTP$ is opened thereby deenergizing the directional stick relay $5S$, which by the closure of its back contact 21^5 included in the energizing circuit for

the mechanism $M6$ of the signal $S6$ allows this signal $S6$ to assume its clear position (see Fig. 6H of the drawings). It is, of course, understood that as the train under consideration passed the signal $S3$ and entered upon the track circuit extending from signal $S3$ to signal $S4$ its presence on this track circuit caused closure of the front contact 403^4 of the approach track repeater relay $3-4ATP$. This resulted in the closure of a pick-up circuit for the directional stick relay $3S$ which includes the front contact 403^4 of this approach track repeater relay $3-4ATP$, the front contact 31^3 of the home-magnet HG of the mechanism $M3$ (which has not yet assumed its deenergized position but will presently assume its deenergized position due to the opening of the contact 193^4 of the home code repeater relay $3-4HTP$), includes the front contact 40^6 of the approach code repeater relay $6ATP$ and the winding of the directional stick relay $3S$. As soon as this directional stick relay $3S$ has assumed its attracted position it will be stuck up through its stick circuit 32^3 and front contact 403^4 of the approach track repeater relay $3-4ATP$ and upon dropping of the home magnet HG of the mechanism $M3$, will be stuck up through a supplemental stick circuit including the back contact 31^3 of the magnet HG of the mechanism $M3$. With this directional stick relay $3S$ energized and with the magnet HG of the mechanism $M3$ deenergized a caution circuit for the mechanism $M5$ is closed which caution circuit includes the back contact 22^3 of the relay $3-4ITPP$, the back contact 63^3 of the magnet HG of the mechanism $M3$ and the front contact 24^3 of the directional stick relay $3S$. This caution circuit will energize the mechanism $M5$ to its caution position in which position the magnet HG is energized, but the magnet DG is deenergized thereby causing the spectacle of the signal $S5$ to be operated to its caution yellow position. Since the signals $S5$ and $S6$ now assume their caution and clear position, respectively, the signal lamps for the signals $S5$ and $S6$ as well as the lamp for the signal $S5A$ will all be extinguished, this for the reason that back contacts 46^5 and 46^6 of the mechanisms $M5$ and $M6$ are both open. In all other respects the signals to the rear of the west-bound train under consideration remain the same in the absence of other trains on the system.

Let us now assume that the west-bound train moves from the track section between signals $S3$ and $S4$ into the track section extending from signal $S1$ to $S4$, that is, moves from the position it occupies in Fig. 6H of the drawings to the position occupied in Fig. 6I of the drawings. This change in the position of the train does not change any of the signal indications illustrated in Fig. 6I from that shown in Fig. 6H but this movement of the train by the opposing signal $S4$ changes the indicating conditions of that signal at the west end of the passing siding A which governs east-bound traffic into the west end of the passing siding A to assume the danger position instead of the caution position and thereby causing the illumination of the two signals associated therewith to cause signal indications to be given as indicated at the west end of the passing siding B in Fig. 6C of the drawings. Since the control circuits extending by the passing siding A are the same as those extending by the passing siding B , it is believed unnecessary to describe the actual circuit changes that take place.

As the west-bound train under consideration

now passes the signal S1 (see Fig. 6J) and enters upon the detector track circuit associated with the east end of the passing siding A no other change in signal indications or illuminations than the placing of the signal S1 in stop position takes place. This signal S1 is operated to its stop position by the presence of the west-bound train on the detector track circuit containing detector track relay DTE (see Fig. 4A) by causing dropping of this detector track relay. The dropping of this detector track relay DTE causes the mechanism M1 for the signal S1 to be deenergized by the opening of the front contact 43DE directly included in the energizing circuit for the mechanism M1. Since it is assumed that the rear end of the train under consideration still occupies the track section extending from signal S1 to S4 no change in the signal aspects to the rear of the west-bound train takes place.

Let us now assume that the west-bound train under consideration proceeds upon the main track of the passing siding A to an extent to entirely clear the detector track circuit associated with the east end of this passing siding A, that is, that this train assumes a position as illustrated in Fig. 6K as distinguished from the position it assumed in Fig. 6J. It is, of course, understood that the train under consideration as it passed the signal S1 caused the directional stick relay 1S to be picked up through a pick-up circuit including the back contact 40^{DE1} of the detector track relay DTE and the front contact 31¹ of the HG magnet of the mechanism M1. With this directional stick relay 1S once energized it will be stuck up and maintains closed its front contact 59¹ (the contact 58¹ in multiple therewith now being open) so as to allow the inductive track repeater relay 2TPI to be intermittently picked up upon each dropping of the track relay 2T so as to transmit an inverse code from the west end of the track circuit extending from signal S1 to signal S4 to the east end of this track circuit. This inverse code in turn causes the inverse code repeater 2ITPP to remain continuously energized, to thereby allow an inverse code to be transmitted from west to east through the track circuit extending from signal S4 to signal S3. This inverse code in turn causes the inverse code repeater relay 3-4ITPP (see Fig. 4C) to be energized to cause the signal S5 to be changed from its caution to its clear position. Also, with the mechanism M1 assuming its deenergized position and with the front contact 42DE of the detector track relay DTE and the front contact 19² of the home track repeater relay 2HTP now reclosed, the approach home relay 3AHD (see Fig. 4B) is energized to its caution position in which its polar contacts assume the left-hand position, which polar contacts and associate neutral contacts 37³ and 38³ in turn cause the mechanism M3 for the signal S3 to be energized to its caution position, with its magnet HG energized and its magnet DG still deenergized, as a result of which the spectacle of signal S3 is operated to its caution position with its signal lamp deenergized because the back contact 46³ operated by the home magnet HG is now open. The west-bound train has now been taken entirely through the passing siding B and the single track section extending from the passing siding A to the passing siding B, and it has been pointed out how the progress of this west-bound train over that portion of the railway system changes the signal aspects and illuminations of the signal lamps.

In each of Figs. 7A to 7I, inclusive, have been illustrated two single track sections jointed by a passing siding B and terminating at the ends of two other passing sidings A and C together with the signals of a signal system such as illustrated in Figs. 4A to 4E, inclusive, illustrating the aspects of these various signals as two trains moving toward each other make a passing meet on the passing siding B. In Fig. 7A the east-bound train has been shown on the main track of passing siding A and the west-bound train has been shown on the main track of passing siding C. By reason of the provision of a caution tumble-down feature rendered active by trains standing on the main track of passing sidings A and C, or due to a track switch directly ahead of one of these trains assuming its reverse position, the signals S3, S5, S10B and S8 assume the caution position as illustrated. As the two trains progress by their starting or head-block signals S2 and S13B, respectively, the usual danger tumble down of signals occurs, thereby causing the signals S3, S5, S10B and S8 to assume the stop position and the two next signals in the rear thereof namely, the signals S9, S11B, S6 and S4 to assume the caution position, all as illustrated in Fig. 7B of the drawings.

Referring to Fig. 7C as the east-bound train passes the opposing signal S1 and the west-bound train passes the opposing signal S12B, the signal aspects in advance of the train are not changed except that the caution signals S4 and S11B become lighted due to the closure of their approach lighting circuits. Referring to Fig. 4B the signal S4 had its signal lamp L4 illuminated in response to the closure of the front contact 58² of the approach code repeater relay 2ATP, a similar circuit being provided for the lamp of the signal S11B.

As the east-bound train now passes the signal S4 and the west-bound train accepts and passes the signal S11B (see Fig. 7D), no change of the signal aspects in advance of the trains takes place, but the signals S4 and S11B which were just passed by these trains have been changed from their caution "Y" to their stop "R" position. Also, because these trains have vacated the track sections directly behind the signals S4 and S11B, respectively, the second signal in the rear thereof, namely, the signals S2 and S13B have been changed from their stop or "R" position to their caution or "Y" position. This change in the aspects of the signals S2 and S13B causes them to become dark signals because the back contacts 46 of their respective signal mechanisms M have been opened to extinguish their respective signal lamps.

As the west-bound train now passes the opposing signal S3 it renders effective the usual passing siding overlap and changes the aspect of the signal S9 from a caution or "Y" aspect to a stop or "R" aspect. In a similar manner the west-bound train upon passing the opposing signal S10B renders effective the usual passing siding overlap and changes the signal S6 from a caution signal to a stop signal.

If the two trains were now to progress into the detector track circuit sections associated with the passing siding B no change of any kind of the various signals would take place. Let us assume that both of the trains have been provided with train orders and that these train orders instruct the east-bound train to take the main track and the west-bound train to take the side track of the passing siding B, and that the brake-

man of the west-bound train opens the track switch at the east end of the passing siding B and that the two trains pass into the passing siding, the east-bound train entering upon the main track and the west-bound train entering upon the side track of the passing siding B, as illustrated in Fig. 7G of the drawings. Let us further assume that the brakeman of the west-bound train recloses the track switch at the east end of passing siding B and throws the track switch at the west end of the passing siding B to its take-siding position. This causes the contact 48^{sww} to be opened and contact 49^{sww} to be closed, thereby opening the circuit for the mechanism M5 and closing the circuit for the mechanism M5A, as a result of which the signal mechanism M5A is controlled in accordance with traffic conditions in advance and accordingly moves the spectacle of the signal S5A to its clear or "G" position to clear this signal S5A (assuming clear traffic conditions ahead) as illustrated in Fig. 7G. Furthermore, this operation of the switch at the west end of the passing siding B to the take-siding position results in the opening of the switch repeating contact 53^{sww}, thereby causing the caution tumble down in advance of the switch points to take place by reason of the deenergization of the inductive kick repeater relay 8TPI (see Fig. 4D), resulting in the placing of the signal S2 in its caution position, the signal S4 having formerly assumed its caution position by reason of the presence of the east-bound train on the main track of the passing siding B. In a similar manner, the presence of the east-bound train on the main track of the passing siding B results in the deenergization of the inverse code track repeater relay 9-6ITPP (see Fig. 4E) and the opening of its front contact 56⁹⁻⁶ included in the energizing circuit for the inductive kick repeater relay 8TPI. For reasons heretofore given, the deenergization of this relay 8TPI results in a caution tumble down taking place in the single track section extending from the passing siding B to the passing siding C. This results in the signals S11B and S13B assuming the caution position as illustrated in Fig. 7G of the drawings.

As the east-bound train now progresses to a point where it deenergizes the detector track circuit at the east end of the passing siding B and the west-bound train progresses by the signal S5A and deenergizes the detector track circuit associated with the west end of the passing siding B (see Fig. 7H), the usual danger tumble down takes place, thereby causing the signals S11B, S13B, S4 and S2 to assume the danger or "R" position as illustrated in Fig. 7H of the drawings.

Let us now assume that the two trains in question progress to a point where their front axles have entered the two single track sections respectively. The only change that this advance of the two trains makes in the signal aspects is that it changes the dark signals S3 and S10B to illuminated signals as illustrated in Fig. 7I as distinguished from Fig. 7H.

By referring generally to Figs. 7A to 7I, inclusive, it immediately becomes apparent that proper safeguard is provided in spite of the fact that the braking distance between these signals S4 and S3 and the signals S10B and S11B is less than double braking distance. In fact, it is readily apparent that each of these trains encounters a caution intermediate signal in one single track section when a train in the other single

track section is still beyond both of the intermediate staggered signals for the opposite single track section.

By referring to Figs. 1A-1E and 4A-4E, it will be seen that many of the relays are shown shaded either at the bottom or at both the top and the bottom. Shading at the top of a relay signifies that it is slow to pick up and shading at the bottom signifies that it is slow to drop and shading at both the top and the bottom signifies that the relay is slow to pick up and slow to drop. Also, if a relay is shunted by a single wave rectifier this signifies that the relay is particularly slow dropping. All of the code pulse following relays are preferably two position polar relays. All track relays (except detector track relays), inverse track relays, and approach track relays fall in this class. Polar relays are used for this purpose, because they are somewhat quicker acting. The inductive kick repeater relays TPI of Figs. 4A-4E are two-position polar relays for the reason that they must pick up only if the induced current impulse is of a particular polarity. The electro-magnets DG and HG of the searchlight signals shown in Figs. 4A-4E are both slow dropping and in addition thereto the home electro-magnet HG has armature retained characteristics, that is, will not drop due to pole changing of the current applied thereto. This operating characteristic is due to the fact that the actual current flow in its winding is not pole changed but continues to flow in the same direction by reason of the full-wave rectifier employed in connection therewith.

The application has thus shown and described rather specifically two railway signaling systems of the absolute-permissive block type embodying the present invention, of which the first system employs a single track section that is long enough to afford two permissive signals for each direction of traffic through the single track section and of which the second is a modified form of the invention in which the single track section is only long enough to afford two permissive signals therein, which permissive signals are spaced from each other less than two times braking distance.

It is desired to be understood that these specific illustrations of applicant's invention have been resorted to primarily for the purpose of disclosing his invention and its applicability to both long and short single track sections and these illustrations have not been resorted to for the purpose of showing the scope of the invention or the extent of its applicability to existing railroads; and it is desired to be understood that various changes, modifications, and additions may be made to adapt the invention to the particular problem encountered in practicing the same, all without departing from the spirit or scope of the invention, except as demanded by the scope of the following claims.

What I claim as new is:

1. In combination, a section of railway track, a track circuit for said section including a source of current at one end and a track relay at the other end of said section included in series, an electro-responsive device, a pair of line wires extending along said section of track, a line relay and a source of current for each end of said pair of line wires, contacts operated by said electro-responsive device for intermittently opening and closing said track circuit and for in synchronism therewith alternately connecting the line relay and the source at that end of said section to that

end of said line circuit, contacts on said track relay for alternately connecting the line relay and the source at the track relay end of said section to said line circuit in synchronism with the connection of the source and the line relay to the opposite end of said line wires, and traffic governing signals controlled by said line relays.

2. In combination, a section of railway track, a track circuit for said section including a source of current at one end and a track relay at the other end of said section included in series, electro-responsive means, a pair of line wires extending along said section of track, a line relay and a source of current at each end of said section, contacts operated by said electro-responsive means for intermittently opening and closing said track circuit and for in synchronism therewith alternately connecting the line relay and the source at that end of said section to that end of said line circuit, contacts on said track relay for alternately connecting the line relay and the source at the track relay end of said section to said line circuit in synchronism with the connections of the source and the line relay to the opposite end of said line wires, a signal at each end of said section governing the movement of traffic into said section from that end governed by the line relay at that end.

3. In combination, a section of railway track, a track circuit for said section including a source of current at one end and a track relay at the other end of said section included in series, electro-responsive means, a pair of line wires extending along said section of track, a line relay and a source of current at each end of said section, contacts operated by said electro-responsive means for intermittently opening and closing said track circuit and for in synchronism therewith alternately connecting the line relay and the source at that end of said section to that end of said line circuit, contacts on said track relay for alternately connecting the line relay and the source at the track relay end of said section to said line circuit in synchronism with the connection of the source and the line relay to the opposite end of said line wires, a directional stick relay which picks up only when a passing train moves in a particular direction associated with each line relay, and a signal associated with each end of said section governing the movement of traffic into that end of said section controlled by the directional stick relay at the opposite end of said section through the medium of the line relay at the said that end of said section.

4. In an absolute-permissive-block signaling system, the combination with a single track stretch of track, signals for governing east-bound traffic through said stretch, signals for governing west-bound traffic through said stretch, a pair of line wires between each pair of successive signals irrespective of the direction in which such signals govern traffic, a track circuit for each section provided with such pair of line wires, a line source and a line relay for each end of each of said pair of line wires, a track relay included in series in said track circuit at one end and a track source included in series in said track circuit at the other end, electro-responsive means at the track source end of said track circuit for intermittently opening and closing said track circuit and alternately connecting that end of the associated pair of line wires to the associated line source and line relay, contacts on the track relay for alternately connecting the line relay and the

line source at that end of such section to said pair of line wires in synchronism with the connection of said line source and said line relay to the other end of said line circuit, whereby the two line relays for each section are alternately controlled by the line source at the other end of said section, means for either opening each line circuit or pole changing the line source included therein in accordance with traffic conditions in the associated section of track and in accordance with traffic conditions in the section next in advance respectively, whereby each line relay is at all times controlled in accordance with traffic conditions in the section with which it is associated and the section next in advance, a directional stick relay associated with each signal, and means for controlling each signal by its associated line relay and by the directional stick relay next in advance.

5. In an absolute-permissive-block signaling system, the combination with a single track stretch of track, signals for governing east-bound traffic through said stretch, signals for governing west-bound traffic through said stretch, a pair of line wires between each pair of successive signals irrespective of the direction in which such signals govern traffic, a track circuit for each section provided with such pair of line wires, a line source and a line relay for each end of each of said pair of line wires, a track relay included in series in said track circuit at one end and a track source included in series in said track circuit at the other end, electro-responsive means at the track source end of said track circuit for intermittently opening and closing said track circuit and alternately connecting that end of the associated pair of line wires to the associated line source and line relay, contacts on the track relay for alternately connecting the line relay and the line source at that end of such section to said pair of line wires in synchronism with the connection of said line source and said line relay to the other end of said line circuit, whereby the two line relays for each section are alternately controlled by the line source at the other end of said section, means for either opening each line circuit or pole changing the line source included therein in accordance with traffic conditions in the associated section of track and in accordance with traffic conditions in the section next in advance respectively, whereby each line relay is at all times controlled in accordance with traffic conditions in the section with which it is associated and the section next in advance, a directional stick relay associated with each signal, a pick-up circuit for each stick relay closed when a train is approaching the signal with which such stick relay is associated, a stick circuit for each stick relay closed so long as the section in advance of the signal with which such stick relay is associated is occupied, means for controlling each line relay by the directional stick relay next in advance, and means for controlling each signal by its associated line relay.

6. In an absolute-permissive-block signaling system, the combination with a track section, a track circuit for said section including a track relay at one end and a track source at the other end connected in series, interrupter means at the source end of said track circuit for intermittently interrupting and reestablishing the current flowing therein, a pair of line wires extending along said track section, a line relay and a line source at each end of said track section, contacts controlled by said interrupter means and

by said track relay for alternately connecting said line wires at the two ends of said track circuit to the associated line relay and the associated line source in a manner that a line relay is connected to one end of said line wires when a line source is connected to the other end of said line wires and vice versa, and means for substantially continuously controlling each of said line relays in accordance with traffic conditions manifested at the other end of said track section over said pair of line wires by controlling the flow of current from such line source.

7. In combination with a single track stretch joining a passing siding having a main track and a non-track circuited side track, of a track switch at the end of said passing siding joining said single track stretch with either said main track or said side track, a head-block signal for governing traffic off of the main track of said passing siding into said single track section, a directional stick relay associated with said signal and in combination with said signal controlling the next signal in the rear, a track circuit for the track section directly ahead of said head-block signal including a track relay, a pick-up circuit for said directional stick relay including a contact closed only if said track switch assumes the take-siding position, and a stick circuit for said directional stick relay including a contact closed only if said track relay assumes its deenergized position.

8. In combination with a single track stretch joining a passing siding having a non-track circuited side track, of a track switch at the end of said passing siding which joins said single track stretch, a head-block signal for governing traffic off of the main track of said passing siding into said single track section, a second signal in the rear of said head-block signal, a directional stick relay associated with said head-block signal and controlling said second signal, a track circuit for the first track section ahead of said signal in said single track stretch including a track relay, a detector track circuit associated with said track switch including a detector track relay, a pick-up circuit for said directional stick relay including a contact closed only when said detector track relay assumes its deenergized position and said track switch assumes the take-siding position, and a stick circuit for said directional stick relay including a contact closed only if said detector track relay assumes its deenergized position.

9. In combination, a passing siding, two head block signals for governing the movement of traffic from the main track and the side track respectively of said passing siding into an adjacent single track section, a third signal to the rear of said head block signals governing the movement of traffic into the main track of said passing siding, a directional stick relay for controlling said third signal, a contact having a front and a back point for each of said head block signals controlled by said respective head block signals, two pick-up circuits for said directional stick relay each including a different one of the front points of the said contacts, and a stick circuit for said stick relay including the back points of said contacts in series.

10. In combination, a passing siding, two head block signals for governing the movement of traffic from the main track and the side track respectively of said passing siding into an adjacent single track section, a third signal to the rear of said head block signals governing the movement of traffic into the main track of said passing siding, each of said signals having a clear electro-mag-

net and a caution electro-magnet, a directional stick relay for controlling said third signal, a contact having a front and a back point for each of said head block signals controlled by the caution electro-magnets of said respective head block signals, two pick-up circuits for said directional stick relay each including a different one of the front points of the said contacts, and a stick circuit for said stick relay including the back points of said contacts in series.

11. In a railway signaling system, the combination with a stretch of track, a track circuit for said stretch including a normally energized relay which is deenergized during occupancy of said stretch, a first signal governing entrance of traffic into said stretch, a second signal for governing the movement of traffic from said stretch into the next stretch ahead and having a home magnet and a distant magnet both of which are picked up if said signal is energized by current of normal polarity and of which the home magnet only is energized if said signal is energized by current of reverse polarity, a directional stick relay, contacts operated by said home magnet for controlling said first signal through a circuit including contacts of said normally energized relay, and contacts on said home magnet for controlling said directional stick relay.

12. In a railway signaling system, the combination with a stretch of track, a track circuit for said stretch including a normally energized relay which is deenergized during occupancy of said stretch, a first signal governing entrance of traffic into said stretch, a second signal for governing the movement of traffic from said stretch into the next stretch ahead and having a home magnet and a distant magnet both of which are picked up if said signal is energized by current of normal polarity and of which the home magnet only is energized if said signal is energized by current of reverse polarity, a directional stick relay for controlling said first signal, contacts operated by said home magnet for controlling said first signal through a circuit including contacts of said normally energized relay, a pick-up circuit for said directional stick relay including a contact closed only if said home magnet assumes its energized position and a stick circuit for said directional stick relay including a contact closed only if said home magnet assumes its deenergized position.

13. In combination with a railway track including the ends of two passing sidings and a single track section connecting them together, a head block signal for each end of said single track section for governing the entrance of traffic into that end of the section, two intermediate signals for said single track section governing traffic in opposite directions, a coded main track circuit for each track section extending from each signal to the next signal in advance and including means for transmitting main pulses of current over the track rails of the section from the source end of said track section to the track relay thereof located at the opposite end, an inverse track circuit for each main track circuit including an inverse track relay at said source end thereof and including means for transmitting inverse pulses between said main pulses over the rails of the section and to said inverse track relay, a line circuit extending from each signal to the next signal in advance, means for causing successive deenergizations of some of said inverse track circuits in response to a train occupying the main track of one passing siding for causing the opposing head block signal to be operated to its caution position,

and means for causing successive deenergizations of said line circuits in response to the entrance of a train into one end of said single track section to cause the opposing head block signal at the far end of said single track section to be operated to its stop position.

14. In an absolute-permissive-block signalling system, the combination with single track stretches of railway track connected by passing sidings, each siding having a main track circuit, a head-block signal for each end of each single track stretch for governing the movement of traffic into such stretch from that end, an intermediate signal for each head-block signal located in advance of such head-block signal for governing traffic in the same direction as said head-block signal, means including a track circuit in one single track stretch for causing one head-block signal and the intermediate signal immediately in advance thereof in said one single track stretch to indicate caution when an opposing train occupies the main track circuit of the passing siding in advance of such one head-block signal, means including another track circuit in said one single track stretch for causing said one head-block signal and its associated intermediate signal of said one single track stretch to indicate stop and to cause the intermediate signal in the next single track stretch to the rear of such head-block signal and governing traffic in the same direction as such head-block signal to indicate caution when said opposing train moving in the same direction enters said one single track stretch.

15. In an absolute-permissive-block signalling system, the combination with two single track sections of railway connected by a passing siding, a head-block signal for each single track section for governing the movement of traffic into such section in a direction toward said passing siding, an intermediate signal for each of said single track sections located in advance of said head-block signal for governing traffic in the same direction as said head-block signal, means including coded track circuits for causing the head-block signal and the intermediate signal immediately in advance thereof in one single track section to indicate caution when an opposing train occupies the main track of said passing siding, and means including line wires for causing said head-block signal and said intermediate signal of said one single track section to indicate stop when said opposing train enters said one single track section.

16. In an absolute-permissive-block signalling system, the combination with two passing sidings connected by a single track stretch, a head-on block signal for each passing siding for governing the movement of traffic from the main track of such passing siding into said single track stretch, an intermediate signal for each of said head-block signals located in advance thereof and for governing traffic in the same direction, means including a track circuit in said single track stretch for causing the head-block signal associated with one passing siding and the intermediate signal immediately in advance thereof and governing traffic in the same direction to indicate caution when the main track of the passing siding in advance thereof is occupied by a train approaching said single track stretch, and means including another track circuit in said single track stretch for causing such head-block signal associated with said one passing siding and the intermediate signal directly in advance thereof to be operated to their stop condition in response to

the entrance of an opposing train into the opposite end of said single track stretch.

17. In an absolute-permissive-block signaling system, the combination with two passing sidings connected by a single track stretch, a head-block signal for each passing siding for governing the movement of traffic from the main track of such passing siding into said single track stretch, an intermediate signal for each of said head-block signals located in advance thereof and for governing traffic in the same direction, means including a track circuit of the main track of one passing siding and including a track circuit of said single track stretch for causing the head-block signal adjacent the other passing siding and the intermediate signal immediately in advance thereof and governing traffic in the same direction to indicate caution when the main track of said one passing siding is occupied by a train approaching said single track stretch, means including another track circuit of said single track stretch for causing such head-block signal and the intermediate signal directly in advance thereof and governing traffic in the same direction to be operated to their stop condition in response to the entrance of an opposing train into the opposite end of said single track stretch, and means including directional stick relay means for causing such head-block signal to go to caution when the intermediate signal in advance thereof is at stop due to the presence of a train which just accepted and passed such intermediate signal and for causing such head-block signal to go to clear in response to operation of the intermediate signal in advance thereof to caution in response to the movement of a departing train moving in the direction in which such signals govern traffic out of the block in advance of such intermediate signal.

18. In an absolute-permissive-block signaling system, the combination with a single track stretch divided by insulating joints into two end sections and one middle section, a head-block signal at each end of said single track stretch for governing the movement of traffic into that end of such stretch, an intermediate signal for each of said head-block signals each located between the first end section and the middle section in advance thereof and governing traffic in the same direction, said intermediate signals governing traffic into opposite ends of the middle track section of said single track stretch, means for transmitting a driven code in a track circuit for each end section from the intermediate signal to the head-block signal in the rear thereof and for transmitting an inverse code in the opposite direction in the track circuit for such track section, means for transmitting a driven code of either a first or a second rate in one direction through the track circuit for said middle section and for transmitting an inverse code in the opposite direction, a circuit for each section for transmitting controls in each direction including line wires, means for causing said signals to normally indicate clear and for causing the inverse code to be discontinued in the first end section and the middle section when a train occupies a track section to the rear of one of said head-block signals and to cause pole changing of the line circuit for the far end section to cause the opposing intermediate and head-block signals to assume the caution position and to cause successive deenergization of said line circuits for controlling the opposing signals to stop when a train enters such single track section.

19. In an absolute-permissive-block signaling system, the combination with a single track stretch divided by insulating joints into a middle section and two end sections, a head-block signal at each end of said single track stretch for governing the movement of traffic into that end of such stretch, an intermediate signal for each of said head-block signals located in advance thereof and at the junction between the first end section and the middle section and governing traffic in the same direction, said intermediate signals governing traffic into opposite ends of the middle track section for said single track stretch, a track circuit for each section, means for transmitting a driven code in the track circuit for each end section from the intermediate signal toward the head-block signal in the rear thereof and for transmitting an inverse code in the opposite direction in the track circuit for such track section, means for transmitting a driven code of either a first or a second rate in one direction through the track circuit for said middle section and for transmitting an inverse code in the opposite direction, a circuit for each section for transmitting controls in each direction and including line wires, means for causing said signals to normally indicate clear and for causing the inverse code to be discontinued in the track circuit of the first end section when a train occupies a track section to the rear of one of said head-block signals to cause the driven code in the middle section to change in rate and to cause pole changing of the line circuit for the other end section to cause the opposing intermediate and head-block signals to assume the caution position and to cause successive deenergization of said line circuits when a train enters such single track section to cause both of the opposing signals to assume the stop position.

20. In an absolute-permissive-block signaling system, the combination with a single track stretch having end track sections, a head-block signal for each end of said stretch to govern entrance of traffic into said stretch, track circuit code communication means for each of said end sections for communicating signal controls through the track rails by driven and inverse codes, the transmission of said inverse codes being normally effective and being in a direction away from the associated head-block signal, line circuit signal communication means for each end section normally effective for communicating polar controls in a direction along such end section toward the associated head-block signal, the control transmitted by the line circuit communication means to the head-block signal associated with that end section being of a particular polarity only if an inverse code is present in the other end section, means responsive to the approach of a train toward one head-block signal for causing the cessation of the inverse code in the adjacent end section, means for applying a control of the opposite polarity to the line circuit signal communication means of the other end section and controlling the other head-block signal in response to such inverse code cessation, means responsive to the entrance of a train into one end of said stretch for rendering said line circuit signal communication means adjacent the other end ineffective to transmit a control of either polarity to the other head-block signal, and signal control means for each of said head-block signals effective to hold such signal at clear if said particular polar control is received, for causing it to indicate caution if a control of said opposite polarity is received and for causing such signal to indicate

stop if said line circuit means is ineffective to transmit a control of either polarity.

21. In an absolute-permissive-block signaling system, the combination with a single track stretch having end track sections, a head-block signal for each end of said stretch to govern entrance of traffic into said stretch, track circuit code communication means for each of said end sections for communicating signal controls through the track rails of such section by driven and inverse codes, the transmission of said inverse codes being normally effective and being in a direction away from the associated head-block signal, line circuit signal communication means for each end section normally effective for communicating polar controls in a direction along such end section toward the associated head-block signal, the control transmitted by the line circuit communication means to the head-block signal associated with that end section being of a particular polarity only if an inverse code is present in the other end section, an intermediate signal for each head-block signal governing traffic in the same direction and located at the far end of the associated end section, means responsive to the approach of a train toward one head-block signal for causing the cessation of the inverse code in the adjacent end section, means for applying a control of the opposite polarity to the line circuit signal communication means of the other end section for controlling the other head-block signal in response to such inverse code cessation, means responsive to the entrance of a train into one end of said stretch for rendering said line circuit signal communication means ineffective to transmit a control of either polarity to the other head-block signal, signal control means for each of said head-block signals effective to hold such head-block signal at clear if said particular polar control is received, for causing it to indicate caution if a control of said opposite polarity is received and for causing such signal to indicate stop if said line circuit means for the section in advance of such signal is ineffective to transmit a control of either polarity, and signal control means for each of said intermediate signals to hold such intermediate signal at clear if an inverse code is received at its end of the track section in advance thereof, for causing it to indicate caution upon cessation of such inverse code, and for causing such signal to indicate stop if the end section in advance thereof is occupied by an opposing train.

22. In an absolute-permissive-block signaling system, the combination with a single track stretch having end track sections, a head-block signal for each end of said stretch to govern entrance of traffic into said stretch, track circuit code communication means for each of said end sections for communicating signal controls through the track rails of such section by driven and inverse codes, the transmission of said inverse codes being normally effective and being in a direction away from the associated head-block signal, line circuit signal communication means for each end section normally effective for communicating polar controls in a direction along such end section toward the associated head-block signal, the control transmitted by the line circuit communication means to the head-block signal associated with that end section being of a particular polarity only if an inverse code is present in the other end section, an intermediate signal for each head-block signal governing traffic in the same direction and located at the far end of the associated end sec-

tion, means responsive to the approach of a train toward one head-block signal for causing the cessation of the inverse code in the adjacent end section, means for applying a control of the opposite polarity to the line circuit signal communication means of the other end section for controlling the other head-block signal in response to such inverse code cessation, means responsive to the entrance of a train into one end of said stretch for rendering said line circuit signal communication means ineffective to transmit a control of either polarity to the other head-block signal, head-block signal control means for each of said head-block signals effective to hold such head-block signal at clear if said particular polar control is received, for causing it to indicate caution if a control of said opposite polarity is received and for causing such signal to indicate stop if said line circuit means for the section in advance of such signal is ineffective to transmit a control of either polarity, intermediate signal control means for each of said intermediate signals to hold such intermediate signal at clear if an inverse code is received at its end of the track section in advance thereof, for causing it to indicate caution upon cessation of such inverse code, and for causing such signal to indicate stop if the end section in advance thereof is occupied by an opposing train, means including said head-block signal control means to cause each of said head-block signals to indicate stop if the end section in advance thereof is occupied by a train departing from such signal and to cause it to indicate caution when such train has passed the associated intermediate signal in advance, and means including said intermediate signal control means to cause each of said intermediate signals to indicate stop if the section in advance thereof is occupied by a train departing from such signal and to cause it to indicate caution when such train has passed the next signal in advance of such intermediate signal.

23. In an absolute-permissive-block signaling system, the combination with a single track stretch divided into sections by insulating joints including two end sections and an intermediate section, signal communicating means for each of said sections for communicating signal controls through the rails of said section in each direction, a head-block signal for each end of said stretch for governing the movement of traffic into said stretch, an intermediate signal for each of said head-block signals governing traffic in the same direction as such head-block signal and located in advance thereof at the distant end of its end section, means including said signal communicating means for normally holding said signals at clear, means including said signal communicating means and including a track circuit to the rear of one of said head-block signals responsive to the approach of a train to a head-block signal for causing the opposing head-block and associated intermediate signal in advance thereof to indicate caution, and means including said signal communicating means and including a track circuit in the end section in advance of said one head-block signal responsive to the movement of a train past said one head-block signal and into said single track stretch to cause such opposing head-block and associated intermediate signal to indicate stop.

24. In an absolute-permissive-block signaling system, the combination with two single track stretches connected by a passing siding each including a plurality of sections, a head-block sig-

nal for governing traffic from one end of the main track of said passing siding into one of said single track stretches, a first intermediate signal in advance of said head-block signal and governing traffic in the same direction as said head-block signal, an entering signal for governing traffic from the other single track stretch into the other end of said main track and governing traffic in the same direction as said head-block signal, a second intermediate signal to the rear of said entering signal and governing traffic toward said entering signal, signal communicating means for said single track stretches including two track circuits for each section one having its track source at one end and its track relay at the other end and the other having its track source at such other end and its track relay at said one end and a track circuit for said main track, means including said signal communicating means and responsive to the approach of a train toward said one single track stretch and moving in a direction opposite to that in which said signals govern traffic for causing said head-block signal and said first intermediate signal in advance thereof to indicate caution, means including said signal communicating means and responsive to the entrance of said train into said one single track stretch when continuing its movement in the same direction for causing said head-block signal and said first intermediate signal to indicate stop and said second intermediate signal to indicate caution.

25. In an absolute-permissive-block signaling system, the combination with two single track stretches connected by a passing siding, a head-block signal for governing traffic from one end of the main track of said passing siding into one of said single track stretches, a first intermediate signal in advance of said head-block signal and governing traffic in the same direction as said head-block signal, an entering signal for governing traffic from the other single track stretch into the other end of said main track and governing traffic in the same direction as said head-block signal, a second intermediate signal to the rear of said entering signal and governing traffic toward said entering signal, signal communicating means including a coded track circuit for each section of each of said single track stretches and for said main track, means including said signal communicating means and responsive to the approach of a train toward said one single track stretch and moving in a direction opposite to that in which said signals govern traffic for causing said head-block signal and said first intermediate signal in advance thereof to indicate caution, means including said signal communicating means and responsive to the entrance of said train into said one single track stretch in response to its continued movement in the same direction for causing said head-block signal and said first intermediate signal to indicate stop and said entering signal and said second intermediate signal to indicate caution, means including said signal communicating means and responsive to the continued movement of said train in the same direction and past said first intermediate signal for causing said head-block signal and said entering signal to indicate caution.

ing signal to indicate stop and said second intermediate signal to indicate caution, and means including said signal communicating means and responsive to the movement of a train through said main track and single track stretches in the opposite direction for causing the first of said signals immediately in the rear of such train to indicate stop and the second of said signals to the rear of such train to indicate caution.

26. In a railway signaling system, in combination, a section of railway track, a pair of line wires paralleling said track section, a coding device located at one end of said track section and having contacts continuously actuated between a first and a second position, means effective in one position of the contacts of said coding device to connect a source of energy across the rails of said section, a code following track relay at the other end of said section operated by energy supplied over the section rails and having contacts movable between a first and a second position, the apparatus being arranged so that as long as said track section is vacant the contacts of said coding device and of said track relay are moved between their two positions substantially in synchronism, a detector relay having normally released contacts, means effective when and only when said track relay is responding to code energy to supply energy to said detector relay, a first and a second control relay, means including a front contact of said detector relay for supplying energy over said line wires to said first control relay when the contacts of said coding device and of said track relay are both in a selected one of their two positions, and means including a front contact of said detector relay for supplying energy over said line wires to said second control relay when the contacts of said coding device and of said track relay are both in the other one of their two positions.

27. In a railway signaling system, in combination, a section of railway track, a pair of line wires paralleling said track section, a coding device located at one end of said track section and having contacts continuously actuated between a first and a second position, means effective in one position of the contacts of said coding device to connect a source of energy across the rails of said section, a code following track relay at the other end of said section operated by energy supplied over the section rails and having contacts movable between a first and a second position, the apparatus being arranged so that as long as said track section is vacant the contacts of said coding device and of said track relay are moved between their two positions substantially in synchronism, a detector relay having normally released contacts, means effective when and only when said track relay is responding to coded energy to supply energy to said detector relay, a first control relay located at one end of said line wires, a second control relay located at the other end of said line wires, means including a front contact of said detector relay for supplying energy over said line wires to said first control relay when the contacts of said coding device and of said track relay are both in a selected one of their two positions, and means including a front contact of said detector relay for supplying energy over said line wires to said second control relay when the contacts of said coding device and of said track relay are both in the other one of their two positions.

28. In a railway signaling system, in combination, a section of railway track, a pair of line

wires paralleling said track section, a coding device located at one end of said track section and having contacts continuously actuated between a first and a second position, means effective in one position of the contacts of said coding device to connect a source of energy across the rails of said section, a code following track relay at the other end of said section operated by energy supplied over the section rails and having contacts movable between a first and a second position, the apparatus being arranged so that as long as said track section is vacant the contacts of said coding device and of said track relay are moved between their two positions substantially in synchronism, a detector relay having normally released contacts, means effective when and only when said track relay is responding to coded energy to supply energy to said detector relay, a first polarized control device, a second polarized control device, means including a front contact of said detector relay for supplying to said first polarized control device over said line wires when the contacts of said coding device and of said track relay are both in a selected one of their two positions energy which at times is of one polarity and at other times is of the other polarity, and means including a front contact of said detector relay for supplying to said second polarized control device over said line wires when the contacts of said coding device and of said track relay are both in the other one of their two positions energy which at times is of one polarity and at other times is of the other polarity.

29. In a railway signaling system, in combination, a section of railway track, a pair of line wires paralleling said track section, a coding device located at one end of said track section and having contacts continuously actuated between a first and a second position, means effective in one position of the contacts of said coding device to connect a source of energy across the rails of said section, a code following track relay at the other end of said section operated by energy supplied over the section rails and having contacts movable between a first and a second position, the apparatus being arranged so that as long as said track section is vacant the contacts of said coding device and of said track relay are moved between their two positions substantially in synchronism, a detector relay having normally released contacts, means effective when and only when said track relay is responding to coded energy to supply energy to said detector relay, a first polarized control device at one end of said line wires, a second polarized control device at the other end of said line wires, means including a front contact of said detector relay for supplying energy over said line wires to said first polarized control device when the contacts of said coding device and of said track relay are both in a selected one of their two positions energy which at times is of one polarity and at other times is of the other polarity, and means including a front contact of said detector relay for supplying to said second polarized control device when the contacts of said coding device and of said track relay are both in the other one of their two positions energy which at times is of one polarity and at other times is of the other polarity.

30. In combination, a stretch of railroad track having a first and a second passing siding which are connected by a single track portion over which traffic moves in both directions, the rails of the single track portion being divided by insulated joints into a plurality of successive block sec-

tions, each block section having at the end thereof or nearest the first passing siding a signal governing entrance into the block section of trains moving from the first to the second passing siding, the signals each being capable of displaying a plurality of indications, the signal for the block section adjacent the first passing siding being capable of providing a clear indication and at least one restrictive indication, each section having means governed by traffic conditions in said section and controlling the signal for such section, and means responsive to occupancy of the portion of the track stretch beside the second passing siding and controlling the signal for the block section adjacent the first passing siding in such manner as to permit the display of the clear indication by said signal only when the portion of the track stretch beside the second passing siding is vacant or is occupied by a train entering said track portion from the single track portion.

31. In combination, a stretch of railroad track having a first and a second passing siding which are connected by a single track portion over which traffic moves in both directions, a first signal at the end of the single track portion adjacent the first siding and a second signal at the end of the single track portion adjacent the second siding, said signals controlling entrance of trains into the single track portion and each being capable of displaying a stop, a clear, and at

30

least one restrictive proceed indication, a first control means governed solely by traffic conditions in said single track portion for at times causing said first signal to display its stop indication, at other times to display a restrictive proceed indication, and at still other times to permit said first signal to display its clear indication, means responsive to traffic conditions in the portion of the track stretch beside the second passing siding and cooperating with said first control means to cause said first signal to display its clear indication only when the portion of the track stretch beside the second passing siding is vacant or is occupied by a train entering said track portion from the single track portion, a second control means governed solely by traffic conditions in said single track portion for at times causing said second signal to display its stop indication, at other times to display a restrictive proceed indication, and at still other times to permit said second signal to display its clear indication, and means responsive to traffic conditions in the portion of the track stretch beside the first passing siding and cooperating with said second control means to cause said second signal to display its clear indication only when the portion of the track stretch beside the first passing siding is vacant or is occupied by a train entering said track portion from the single track portion.

THOMAS J. JUDGE.
